UNITED STATES PATENT OFFICE.

MAURICE SAMBURG AND JULIUS C. HOCHMAN, OF NEW YORK, N. Y.

COMPUTING MACHINE.

Application filed December 16, 1920, Serial No. 431,154. Renewed February 12, 1926.

Our present invention relates to computing machines and more particularly to machines for performing the operation of addition and preferably also that of subtraction.

5 An object of the invention is to provide a mechanism of the above type which shall be compact, light and simple in construction, yet reliable in action under hard usage. 10 Another object is to provide a computing mechanism of the type referred to, of such construction that it can be readily associated with a common form of printing mechanism, such, as for instance, an ordinary 15 typewriter to cause the latter to print the numbers concurrently with the actuation of the computing mechanism, and certain features of the invention reside in a novel combination of our computing mechanism with 20 such typewriter or other printing mechanism.

Another object is to provide a computing and printing machine of flexible character to suit various kinds of work and which 25 shall not require special forms, and which shall more particularly be susceptible of performing all or any combination of the following functions: making vertical or 30 sheet, adding dollars, weights, quantities or any other units, punctuating the numbers as desired and making in one operation any number of carbon copies, including the sums figured.

35 Another object is to provide a computing mechanism which when associated with any ordinary typewriter will not impose on the latter any strain or force greater than those imparted to it in ordinary operations for 40 corresponding purposes and will still allow said typewriter to be operated at all times without actuating any part of the computing machine and through all functions, identically as though the computing mechanism 45 were not attached thereto.

Another object is to provide a computing mechanism which can be attached to all typewriters as at present made free from mechanical connection with any operating part thereof, and which will be in operative position relative to the typewriter key bars, even though the spacing of the key-bars on

the several typewriter makes may vary considerably.

Another object is to provide accurate 55 computing mechanism susceptible of cooperation with a typewriter to cause the latter to correctly print concurrently with the actuation of the former; and this although the keystroke of the typewriter is appreciably greater or less than that of the computing mechanism.

Another object is to provide a computing mechanism which when attached to a typewriter will allow the typewriter to be used 65 on the ordinary "drophead" type of desk without interfering with the closing thereof, and which will not necessitate chopping into the desk in any way in order to obtain this result.

70 In a preferred embodiment for carrying out the above objects, we provide a complete self-contained computing machine of dimensions and arrangement such that it can readily be mounted on the frame of many 75 of the common makes of typewriters, above and free from interference with the normal operation of the typewriter keyboard, the above mentioned printing by the typewriter concurrently with the arithmetical operation by the computing mechanism being effected by a disposition of keys or other actuating members of the latter, at such intervals that when the device is mounted upon the typewriter, the number key members of 80 the latter are in the path of operation of 85 the former. The typewriter platen can, therefore, be shifted at will in the course of 90 addition, either laterally or circumferentially to suit the particular form being used and the typewriter keyboard may be operated to print any characters without interference with the accuracy of the arithmetical 95 operation performed by actuation of the computing attachment.

Our computing attachment although 100 preferably employed in the relation above set forth may be used to advantage apart from a typewriter in which event the results of computation are readable but neither the numbers nor the sums are printed.

The present application is directed to an improvement on that of our copending application Serial No. 344,239 filed December

11, 1919, in which the foregoing objects are also accomplished. As to all common subject matter, this application is a continuation thereof.

5 The mechanism in the preferred embodiment is so constructed that it will operate with unfailing accuracy whether used as a typewriter attachment or as a separate machine. For this purpose the preferred mechanism is provided with improved means for preventing overthrow by inertia after each operation of the totalizer, for preventing quick repeated operation of a key before return thereof to home position, for preventing a reverse operation of the totalizer during the return of the operative parts to home position after each operation, for insuring shifting of the totalizer through the width of one and only one number wheel 10 after each key depression, for compelling depression of a key when once commenced to be continued to the end of the stroke thereof, for preventing depression of all other keys when any key is wholly or partly depressed, and other safeguarding means referred to hereinafter.

According to another preferred feature, the adding mechanism is provided with means functioning to avoid double actuation 30 by inertia of a typewriter number key-lever and consequent printing of a double digit for any single operation of the adding machine attachment. An auxiliary load is employed for this purpose to resist operation more particularly of the keys of lower number value. In the preferred embodiment a differential loading means is employed to produce equal resistance on all keys, this resistance being equal at all times to the greatest resistance met in normal actuation of the most fully loaded key, namely the number 9.

According to another feature, the adding mechanism is reversible in character, and 45 reversing gear means is provided, readily accessible from the exterior to set the mechanism for direct subtraction.

Other objects and features will appear hereinafter.

50 Referring now to the drawings, in which is shown a preferred embodiment of the several features of our invention.

Fig. 1 is a front elevation of the typewriter with our mechanism applied thereto,

55 Fig. 2 is a top view thereof.

Fig. 3 is a sectional view taken along the line 3—3 of Fig. 1.

Fig. 4 is a detail view of an adding key.

Fig. 5 is an elevation of our adding machine attachment, the cover of the mechanism being shown in section to reveal the interior parts.

Fig. 5^a is a detail sectional view taken along the line 5^a—5^a of Fig. 5,

Fig. 6 is a sectional view taken along the 65 line 6—6 of Fig. 2,

Fig. 7 is a sectional view taken along the line 7—7 of Fig. 6,

Figs. 8, 9, 10 and 11 are respectively sectional views on an enlarged scale taken 70 along the lines 8—8, 9—9, 10—10 and 11—11 of Fig. 5,

Fig. 12 is an enlarged plan view of the subtraction mechanism and related parts,

Figs. 13 and 14 are sectional views taken 75 along the lines 13—13 and 14—14 of Fig. 12,

Fig. 15 is an enlarged side elevation showing the carrying idlers and totalizer idler gears,

Figs. 16 and 17 are sectional views taken 80 along the lines 16—16 and 17—17 of Fig. 15,

Fig. 18 is a plan of the control plate,

Fig. 19 is an end view of the control plate,

Fig. 20 is a plan of the operating plate,

Fig. 21 is an end view of the operating 85 plate; and,

Fig. 22 is a sectional view taken along the line 22—22 of Fig. 6.

Similar reference characters refer to similar parts throughout the several views of 90 the drawings.

The typewriter and the relation of the adding attachment therewith.

Referring to Figs. 1 and 2, we have shown 95 in general outline a typewriter comprising a frame 1, a platen 2, a keyboard 3 comprising the usual letters, numbers and punctuation keys, and a set of key levers 4, one connected to each key and extending rearwardly 100 therefrom and arranged in any known manner for printing the corresponding character upon a sheet on the platen when a key is depressed. The machine includes the usual escapement not shown for advancing the 105 platen after each key depression.

The general arrangement of parts described is common to the product of the various large typewriter manufacturers, such as the Underwood, the Remington, the 110 Royal, the L. C. Smith and others. Most of the above makes of machines and others are equipped with a name plate 5 secured to the frame 1. Our computing machine is so designed as to be universally applicable with little trouble preferably to the frame 1 of each of the types referred to, serving as a computing attachment to form a combined typewriter and computing machine. Our computing mechanism is, however, complete 115 in itself and may be employed to advantage apart from any typewriter or other printing mechanism, as will appear more fully below.

The computing mechanism is shown in general outline in Fig. 1 and has a base plate 6 and a casing 7 in which is enclosed the computing mechanism. The casing has openings 8 through which may be read num-

- bers on the totalizer wheels registering the results of the various arithmetical operations. The machine is provided with a set of number keys 9, one corresponding to each 5 digit as shown, and a zero key, which may be designated as computing or adding keys to distinguish from the typewriter number keys. Each adding key has associated therewith a key bar 10 slidable in a corresponding groove 11 in the base plate 6, each key bar extending directly over the key lever shank 4 of the corresponding number key on the typewriter as appears best in Figs. 3 and 5, so that depression of any of the computing machine keys will operate the computing mechanism and concurrently therewith will cause depression of the corresponding number key on the typewriter and cause the digit to be printed upon the platen. 10 The width of each key bar extends transversely of the length of the corresponding typewriter key lever so that the above action will take place without need for special connections or aligning means of any sort. 15 The adding keys are preferably mounted at the forward end of brackets 12 secured to the key bars immediately below the bottom of casing 7, the adding keys being raised as shown, in order to provide ample knuckle clearance when operating the top row of typewriter keys. The forward face 13 of the casing slopes downwardly toward the base plate 6, to allow knuckle clearance for operation of the keys 9. A front plate 17 20 extends across the width of base plate 6 and overlaps the lower ends of the key bars, the upper edge of the front plate limiting the depression of the adding key when reached by the key bracket 12. 25 In the various common makes of modern typewriting machines above enumerated and in others, the keyboard is arranged as shown in Fig. 2, the number keys 2 to 9 and zero being located in the fourth or rear row and the L key in the second row serving for printing the digit 1. The key bars of the computing mechanism are so disposed and of such relatively large width as to allow for a considerable variation in the spacing 30 of the typewriter key levers. As at present made the difference in the distance between the number 2 and the number 0 keys is $\frac{1}{8}$ ", yet our adding key bars will coact with these typewriter keys, when attached to either the 35 wide or narrow machines.
- By reason of the fact that typewriters are designed for equal stroke of the keys, and the L key has a longer lever arm than the number keys in the rear row, the portion of 40 the L key lever arm in the plane of the adding key bars will move through a smaller range for a full key depression than will the corresponding portion of the other key levers. The key bar for the number one key 45 is accordingly made correspondingly shorter as shown at 14 (Fig. 5) so that, when the number one adding key is depressed the corresponding typewriter key lever will move through the lesser range required.
- In Fig. 1 the computing machine is shown by way of illustration as mounted on a Royal typewriter. In the Royal machine, the name plate 5 is secured to the frame by means of a pair of screws in the position of screws 15 and 16. A pair of ears 18 and 19 are secured by screws 20 and 21 to the ends of the front plate 17 and under the rear face thereof to come flush with the rear surface of the back plate. Screw-holes near the ends of the ears register with the regulation holes in the name plate of the Royal typewriter so that screws 15 and 16 may readily be inserted through the ears to concurrently secure to the frame, the name plate and computing machine attachment with the key bars directly over the shanks of the corresponding typewriter key levers, as above noted. 50
- The holes for screws 20 and 21 of the computing machine correspond in position with the screws for securing the name plate in place in the Underwood typewriter, so that our computing machine may be attached to the Underwood machine by dispensing with the ears 18 and 19 and putting screws of appropriate length through the holes provided in the front plate 17 and in the name plate of the typewriter, and into the typewriter frame. In the Remington typewriter, there are no screws accessible from the front of the machine, and the computing machine is preferably secured in place by ears having appropriate clamp screws (not shown) coacting with the sides of the frame. The L. C. Smith having its name plate secured to its frame by screws in a still different position, it would only be necessary to provide ears to suit. So by providing a suitable front plate construction as by changing the ears to suit each typewriter, the adding attachment can be easily connected to fit any machine. 55
- It will be seen that the computing machine can be installed as an attachment for Remington, Underwood, Royal, L. C. Smith or other typewriters by any unskilled person and in a fraction of a minute. In most cases it is necessary merely to remove a couple of screws from the typewriter, to place the back plate of the computing machine against the typewriter name plate, screwing the same in position by use of a pair of screws of slightly greater length substituted for the removed screws, and using the same tapped holes in the typewriter frame. There is no adjusting or aligning necessary, since the ears bring the adding keys into exact position for proper operation on each machine. 60
- It will be understood that the features above described can be embodied broadly in 65

multipling, dividing, adding and subtracting machines. In the preferred embodiment, the invention is concerned with adding and subtracting machines. The computing machine will, therefore, be referred to hereafter as an adding machine and the number keys thereof as adding keys.

The lengths of key stroke for the different makes of typewriters differ. In the Remington machine, for instance, the part of the key lever shank in the path of the adding machine key bars has a stroke of 20/32 inch, in the Underwood 18/32 inch, in the Royal 16/32 inch and in other makes, the stroke is within these maximum and minimum limits. The key stroke of our adding machine regardless to which make of typewriter it is to be applied is preferably 19/32 inch and when the attachment is applied to any machine in the manner above described the apparatus will operate satisfactorily in every case.

In the case of the Remington machine, the key bars with the exception of the number 1 key will rest directly on the tops of the corresponding typewriter key lever shanks in the manner diagrammatically shown in Fig. 5. The final 1/32 inch of the typewriter key stroke, the difference between the 20/32 inch stroke of the typewriter and the 19/32 of the adding key, is traversed by reason of the inertia or momentum imparted to the key lever in the above operation.

In the case of the Underwood machine, the bottom of the adding key bar will be 1/32 of an inch above the shank of the typewriter key and, therefore, the attachment key after taking up the short lost motion will push the typewriter key lever through its full stroke.

Features of the adding machine construction.

Referring to the drawings, the key bars 10 in the grooves 11 in the base plate terminate at their upper ends each in a forwardly extending short tongue 22. The casing 7 has end walls 23 and 24 between which extends preferably an operating plate 25 shown by itself in Figs. 20 and 21. The operating plate is provided with a series of rearwardly extending struck-up lugs 26 in stepped relation, as shown, one corresponding to each key, each said struck-up lug being in the path of the tip of tongue 22 on the corresponding key as best shown in Fig. 8. It will be seen that as an adding key is depressed, the key bar moves free of the operating plate until its tongue comes into contact with the corresponding struck-up lug and during the remainder of the key bar movement, the operating plate will travel therewith. The lugs are stepped in such relation that the amount of displacement of the operating plate will be directly proportional to the number value of the key. Thus, the struck-up lug 26⁹ (see Fig. 20) corresponds to the number 9 key and the lug 26²

to the number 2 key, the intermediate lugs corresponding in succession to the number keys of intermediate value. The lug 26¹ to the right of the lug 26⁹ corresponds to the number 1 key. There is no lug at the zero position, consequently for zero actuation the operating plate does not move.

The operating plate 25 has preferably short ledges 27 bent up from the opposite ends thereof, gear teeth 28 being formed on said ledges to form a rack, tongues 29 left continuous with the main length of the bar at the ends of the rack being arranged to slide in corresponding grooves 30 in the end plates 23 and 24. The racks are permanently in mesh with pinions 31 and 32 near the ends of an operating shaft 33 journaled in the end walls 23 and 24. Encircling the operating shaft is a coil torsion spring 34 secured thereto at one end as at 35 and secured at the other end to a fixed point as shown at 36 in Fig. 11. As the operating plate is actuated by depression of any adding key, the rack and pinion connections at the opposite ends will prevent any tilting or binding and the operating plate will move downwardly with a pure movement of translation, rotating the operating shaft and storing energy in the torsion spring 34 which energy will be released to return the operating plate to its upper or home position after the pressure upon the adding key is released.

The impulse from the operating plate through the operating shaft is transmitted to the totalizer, designated in its entirety by letter T, through a master wheel 37 arranged to rotate with a sleeve 39 upon the operating shaft during the operating movement but held against rotation during the return movement thereof to avoid reverse movement of the totalizer. For this purpose, the master wheel is rigidly secured preferably by a screw 38 upon the sleeve 39 which encircles and is free to revolve around the operating shaft and extends toward the left from the master wheel, being held by any desired means against sliding movement along the shaft. A driving connection between the operating shaft and the sleeve is established through a one-way clutch preferably a ratchet clutch 40 near the left end of the operating shaft. The clutch includes a driving clutch member 41 pinned to the shaft and a driven clutch member 42 carrying gear teeth 43 meshing with a gear 44 idly revolving upon a fixed shaft 53 parallel to the operating shaft, the latter gear having formed rigid therewith a second gear 46 which meshes with a master wheel driving gear 47 formed rigidly upon the end of sleeve 39 opposite the master wheel. A compression spring 48 is interposed between gear 47 and clutch member 42 to maintain the clutch operatively connected.

As a result of the above construction, it will be seen that as an adding key is depressed, the operating plate 25 will move downwardly, driving the operating shaft 33 through the rack and pinion connections 31 and 32 and storing energy in torsion spring 34, the torque being transmitted to the master wheel 37 through the teeth of clutch member 42, clutch gear 43, countershaft gears 44 and 46 to the master wheel driving gear 47 and through sleeve 39 to the master wheel 37. The master wheel is thus rotated through an angle proportional to the number value of the depressed key and will advance the totalizer to a corresponding extent. When the pressure of the finger is removed from the adding key, the torsion spring 34 will expand, rotating the operating shaft and with it the pinions 31, 32 thereby returning the operating plate to home position. The clutch 40, however, will open, the driven clutch member being pressed out of engagement with the driving clutch member against the compression of spring 48 so that the master wheel will not be driven in reverse direction.

Tabulating or decimal system and escapement.

The totalizer to be described more fully below, comprises a set of number wheels 50, upon a shaft 51, and a set of totalizer driving idler gears 52 upon a second shaft 53, as best shown in Fig. 17, said sets of number wheels and gears being both supported in a carriage 54 having an operating thumb piece 55 projecting through a slot 62 in the top of casing 7, the other end of the thumb piece which is inside the casing having an extension 60 serving as a stop for setting the totalizer in the correct tabular position for the number to be added. Tabulating keys 56 properly spaced apart are provided preferably in a support 57 on the upper surface of casing 7 and adjacent thumb piece 55, one corresponding to each decimal place within the range of the machine and bearing a corresponding designation preferably as shown in Fig. 2. A compression spring 58 is interposed between the support 57 and the head of each key to urge it upwardly, and each key has a stop 59 integral therewith and within casing 7 arranged in the path of stop bar 60 upon the carriage, so that upon depression of a tabulating key and drawing the thumb bar to the right, the carriage will be set for the addition of any number of the order of the depressed tabulator key. The key of highest order, in the specific embodiment, the M or million key is preferably a dummy, the thumb piece being limited by the end 61 of slot 62 to set it to position for a number of seven digits.

A compression spring 63 is disposed to-

ward the right of the carriage 54 and encircles the shaft 51, urging the carriage toward the left; a pawl and escapement ratchet rack mechanism now to be described, retaining the carriage against the pressure of the spring. The pawl and ratchet mechanism is preferably arranged to be tripped at the lowest point of depression of each key to allow the spring to push the carriage forwardly through the width of one number wheel, preparatory to the adding of the following digit. For this purpose, we preferably pivot a ratchet rack bar 64 as at 65 upon the right-hand end of the carriage. The bar is provided with a lower set of ratchet teeth 66 each having a vertical edge 67 and an inclined edge 68. The distance between successive teeth is equal to the width of a number wheel. At its upper edge the bar has a second set of teeth 69 both the edges of which are inclined as shown. A vertical bar 70 is rigidly secured to a stationary frame bar 71 and has a stationary pawl tooth 72, a coil spring 73 maintaining the lower edge of the ratchet bar in engagement with said pawl tooth as shown, against the expansion of spring 63. A second stationary pawl tooth 74 is directly above the first and is normally clear of the set of teeth 69 at the upper edge of the ratchet. The pawl and ratchet mechanism is tripped by means of a lever 75 pivoted to the frame bar 71 as at 76 and held in inactive position by a spring 77. The lever has an engaging portion 78 coacting with the ratchet bar near its free end to raise the same about its pivot 65, a part 79 on the lever overlapping the ratchet bar to retain the parts in proper alignment. After tripping of the ratchet, the coil spring 63 in its expansion will move the carriage toward the left by one tooth, the inclined face of the succeeding upper ratchet tooth engaging the upper pawl 74, which latter urges the ratchet bar downwardly assisted by contraction of coil spring 73 to prevent shifting through more than one tooth at a time. Since the form of the teeth and the distance between stationary pawls 72 and 74 is just enough to allow escapement ratchet rack 64 to move between them only when in contact with either one or the other of them, it is evident that ratchet rack 64 is positively controlled at all times. This control would of itself prevent the carriage shifting more than one tooth at a time, independent of coil spring 73. Spring 73, however, does serve to speed up the drop of rack 64 in addition to its safeguarding effects.

The lever 75 is preferably tripped by a control plate 80 parallel to and adjacent the base plate 6 and interposed between the key bars 10 and the operating plate 25. The tongues 22 at the ends of the key bars pref-

erably overlap and rest on the upper edge of the control plate as best shown at 81 in Fig. 9, the tips of said tongues as heretofore noted, coming into contact in the course of their downward movement with the corresponding struck-up lugs 26 in the operating plate. As shown, the tripping lever 75 has a tail 82 in the path of the lower edge 83 of the control plate, so that at the end of the depression of each adding key, the control plate causes the tripping heretofore noted.

The key loading means.

When our adding machine is used in combination with a typewriter in the manner above described and in the absence of special provision, a difficulty might be encountered in the printing, more particularly, of the numbers of lower value. As the operator in practice presses the adding keys with equal force, the adding keys of lower number value at the start of the stroke would move considerably faster than the number 9 key, because of the material range of substantially free travel of the former prior to effective engagement with the load actuating operating plate, and then would slow up at the latter part of the stroke when engaged with said loaded operating plate. The typewriter key-levers associated with adding keys of lower number value, due to the initial high speed of actuation and the sudden addition of resistance with consequent reduction of speed of depression, would thus acquire considerable momentum, and might move downwardly in advance of the adding key to print the number, actuate the typewriter escapement to advance the carriage, and be engaged the second time by the adding key bar in its continued downward path to print the number a second time. Also in the case of the number 1 key, the impact of the adding machine key on the typewriter key due to the acceleration gained by the former in its lost motion before touching the typewriter number 1 key shank would provide an additional tendency toward double printing. Thus, it is possible, more particularly, that the number 1 adding key, while accurately operating the totalizer might cause the printing of 11 instead of 1.

To obviate this difficulty we prefer to provide differential loading means to resist the advance more particularly of the adding keys of lower number value, so that excessive momentum shall not be acquired by the corresponding typewriter key-levers and this, without adding to the force required to operate the highest or number 9 key.

In the preferred embodiment, this loading means is arranged to resist the movement of each adding key during the portion of its

stroke prior to operative engagement with the operating plate. For this purpose, we prefer to provide upon the control plate 80, a pair of racks 85 and 86 extending in front of the operating plate as best shown in Fig. 9 by rigid connection with U-shaped bars 85' 70 and 86' which are welded solidly to the control plate 80. The rack 85 is located at a distance from the left end of the control plate sufficient to clear the gears 44, 46, 47 heretofore described and meshes with a gear 75 87 floating upon the operating sleeve 39 which meshes in turn with a pinion 88 pinned to a loading shaft 89 extending the entire width of the casing 7 and journaled as at 90 and 91 in the opposite end walls 23 80 and 24 thereof. The rack 86 on the control plate meshes in similar manner with a floating gear 92 upon the operating shaft which in turn meshes with pinion 93 near the right end of the loading shaft. Encircling the 85 right-hand portion of the loading shaft is a torsion coil spring 94 pinned thereto at one end as at 95 and secured at the other end to a gear 96 floatingly mounted upon said loading shaft and adjacent pinion 93. The gear 96 meshes with a gear 97 fixed upon the operating shaft.

As a result of the above construction, it will be seen that as any adding key is depressed, the advance of the corresponding key bar will cause a downward movement of the control plate, which through its racks 85 and 86 will rotate gears 87 and 92 respectively, the gears 87 and 92 in turn rotating the pinions 88 and 93 on the loading shaft, one function of which is to cause the control plate to move without binding or tilting, that is, in parallel translation. Throughout this action, the floating gear 96 upon the loading shaft is held against rotation by gear 97 upon the operating shaft, since the operating shaft is prevented from rotating by the pull of its coiled spring 34. As a consequence the end 95 of the loading spring rotates with the loading shaft, but 105 the end which is secured to the floating gear 96 is retained against rotation, so that the loading spring will wind up as the adding key is depressed, thus offering sufficient opposition to the depression of the key to prevent gathering of excessive inertia by the typewriter key lever under control thereof and storing additional energy to return the control plate to its upper position when the key is released at the end of its stroke. As 110 soon, however, as the tongue on the end of the key bar comes into engagement with the corresponding struck-up portion 26 on the operating plate, and the latter begins to be depressed thereby, and through the racks 28 rotates the pinions 31 and 32 on the operating shaft, the gear 97 on the operating shaft will rotate the floating gear 96 upon 115 120 125

the loading shaft, so that both ends of the loading spring will be rotated at the same speed and the resisting effect of the loading spring upon the adding key will be eliminated.

It will thus be seen that the loading spring furnishes a substantially constant opposing force to the continuously applied force exerted by the operator in depressing the adding key, this force being removed the instant that the adding key comes into operative engagement with the operating plate. By preference the torsion spring 94 is arranged to offer an opposition approximately equal to that encountered in the actuation of the mechanism for operating the totalizer. Thus, each key is opposed by an auxiliary load during the portion of its stroke prior to engagement with the operating plate. Since the tongue 22 on the number 9 key in the preferred embodiment is at the beginning of its stroke in direct engagement with the corresponding key on the operating plate, the loading mechanism does not come into action for this key, and enters into operation in the case of each of the other keys for an interval varying in an inverse ratio with the number value of the key, so that the total resistance encountered in the actuation of each key shall be equal to that for the number 9 key.

In other words, the loading spring furnishes a variable or differential method of adding a resisting load to the otherwise comparatively free portions of the stroke of the keys of number value less than 9, and this added load will at all times be just enough to make the total key resistance for any key equal to the force of operating the number 9 key. Thus, it is seen that the key resistance on all numbers can be made the same.

A further function of the loading means appears in the next to the last paragraph under heading The master wheel controls.

45 The master wheel controls.

To prevent undue advance of the master wheel by inertia and for other purposes which will appear below, we provide a master wheel governing stop, preferably in the form of a pawl 100 pivoted as at 101 to the frame bar 71 and extending in a plane at right angles to that of the master wheel and having a pointed tooth 103 arranged to enter between teeth of the master wheel. A stop control bar 104 formed preferably of sheet metal has a bent end (see Fig. 22) extending transversely through an opening 105 in the tail 106 of the stop member and provides a shoulder 107 extending transversely between the stop member and the back plate. The upper end of the control bar has a forwardly extending tongue 108 fitting into a notch 109 in the upper edge of the operating plate.

65 In operation, as an adding key is de-

pressed, the master wheel is caused to rotate in the manner heretofore described and at the end of the downward movement of the control plate, the tongue 110 at the lower edge of the latter contacts and depresses the shoulder 107 upon the stop control bar, causing a movement of the stop element about its pivot and an entry of the pointed tooth 103 between teeth of the master wheel, until at the extreme end of the operating movement, the tooth 103 will be fully meshed between teeth of the master wheel and will prevent further movement thereof either forwardly or backwardly. A friction spring lock 111 upon the frame bar 71 adapted to fall into either of two depressions 111' at the back end of stop 100 serves for frictionally locking the stop pawl in either of its two extreme positions, to insure against chance movement of the stop pawl while the control plate is in any intermediate point of its stroke.

When the operator releases the adding key, the coil springs 34 and 94 snap the parts back, as heretofore described. During this return movement, the pawl tooth remains in engagement with the master wheel, locking the same against any shifting movement until the operating plate is near the extreme end of its return movement, whereupon the bottom of the notch 109 therein comes into contact with the tongue 108 on the control bar and raises the tail of the stop pawl, moving the latter against the resistance of the spring lock 111 out of engagement with the master wheel, leaving the latter free for advance in response to a succeeding adding key operation. It will thus be seen that the locking of the master wheel takes place concurrently with the end of the down stroke of the control plate and that the master wheel is maintained in locked position until the extreme end of the return stroke of the operating plate. By this construction, it will be seen that should the adding key be given a second downward impulse by the operator, in the course of its return stroke, such impulse would not affect the totalizer in any way since the governing stop locks the master wheel against displacement until the end of the return stroke.

It will be apparent that the loading shaft and the spring 34 above described will prevent depression of the operating plate at a high rate of speed which might occur in their absence, particularly, for operation of adding keys of the lower number values. Thus, is eliminated the likelihood of acceleration of the operating plate in advance of the adding key, and the consequent excess advance of the master wheel 37.

A pawl roller 112 upon the end of a pivot arm 113 coacts with the master wheel, being held in engagement therewith by a coil spring 114, one end of which is secured to

the frame bar 71 and the other end against the rear edge of the arm 113. This pawl tends to hold the master wheel against undesired movement by vibration at such times as the master wheel governor stop 100 is out of engagement therewith.

The zero operation.

In operation of the zero key, the escapement mechanism for the totalizer carriage is to be operated as for any other adding key, but the master wheel is not to be displaced. The operating plate which actuates the master wheel for the digit keys, is accordingly left stationary for zero key operation. The operating plate being relied upon in the case of the digit keys to return the master wheel locking stop to inoperative position, the end of any such stroke finds the locking stop control bar resting on top of the operating plate. Therefore, for zero operation the locking stop cannot be operated by the control plate at the very end of the control plate's normal full stroke, since any movement of the locking stop would move its control bar downward, and this in turn would pull down the operating plate upon which it rests. It is plain that such actuation of the operating plate for zero operation would result in numerical actuation of the totalizer and so produce an error in the calculation. For this reason, the control plate is so designed as to cause operation of both the escapement mechanism and the master wheel lock for the various digit keys, as above set forth, and to cause operation of the escapement mechanism but not of the master wheel lock for the zero operation in the manner now to be described.

Pivoted upon the control plate as at 115 is an L-shaped lever having a horizontal arm 116 and a vertical arm 117 the upper end of which overlaps a notch 118 in the upper edge of the plate, said upper end being in the path of the finger 22 on the zero key bar 10. A wire spring 119 presses against the free end 120 of the horizontal arm and urges the upper end 121 of the lever upwardly, this upward movement being limited by a stop 119' formed integral with the control plate. A lug 122 at the lower end of the lever and adjacent the rack bar 86 is in the path of a portion 123 on the ratchet operating or tripping lever 75. Upon depression of the zero key, it will thus be seen that for the first small fraction of an inch, the lever 116-117 will be moved about its pivot against the resistance of the wire spring 119 without moving the control plate, the tongue 22 of the zero key entering the notch 118, and thereafter moving the control plate. The control plate, therefore, moves downwardly under the influence of the zero operating key through a range smaller than for the other keys by the depth of notch 118 so

that the tongue 110 at the lower edge thereof will not reach the shoulder 107 of the control bar for the master wheel stop and the master wheel stop will not be actuated. The lug 122 on the lever 116-117 however, moving a distance equal to the full normal range of the control plate, will come into engagement with the tripping lever 75 and will, therefore, cause an advance of the totalizer carriage as for any other adding key.

The full stroke mechanism.

This mechanism is for the purpose of insuring that when any key is operated, it will be depressed to its full extent and operates by preventing the return of any such key until it has been depressed its full stroke. For this purpose each of the key bars is provided with ratchet teeth 125 near its upper portion and the sharp edge 126 of a pawl plate 127 is urged by means of a wire spring 128 into coaction with the teeth of the key bars as will appear in Fig. 8, the pawl plate extending substantially the width of the casing. The pawl plate is preferably pivoted to the side walls of the casing by screws 129 extending through integral ears 130. A full stroke control piece 131 for cooperation with the pawl plate extends substantially the height of the casing 7 and has a tongue 132 overlapping the upper edge of the control plate and an off-set pointed tongue 133 slideable along the base plate and under the edge of the pawl plate and adapted to lift the pawl plate out of engagement with the key bar ratchet teeth at the very bottom of the key stroke. The full stroke control piece has a shoulder 134 between the pointed end and the main length thereof arranged in the path of the control plate. It will be seen that immediately upon the depression of any key, the toothed edge of the pawl plate will come into mesh between teeth of the key bar, and return of the key bar and of the coacting mechanism will not be permitted. When the key is depressed to the extreme end of its downward stroke, the lower edge of the control plate movable therewith comes into engagement with the shoulder 134 upon the full stroke control piece and moves the latter downwardly into engagement with the pawl plate, forcing the latter out of mesh with the ratchet on the key bar, so that upon release of the finger piece, the key bar may be returned to home position. At the very end of this return movement, the upper edge of the control plate comes into engagement with the tongue 132 on the upper end of the control bar and returns the latter to the home position shown in Fig. 5; thereby dropping the pawl plate into contact with the key bars again.

By preference a pair of the full stroke pieces which act simultaneously as above described, are provided, the two members being

best shown in Fig. 6 and indicated by reference characters 131 and 131' one near each end of the casing.

5 *The two-key mechanism.*

To prevent operation of more than one key at a time, we provide a system of stops to lock the remaining key bars against depression when any one key is wholly or partly depressed. For this purpose, we prefer to pivot to the base plate, a plurality of inverted generally T-shaped stop members 135, the cross-bar 136 of each stop member extending preferably from midway between the sides of the key bar 10 on one side thereof to midway between the sides of the key bar on the other side thereof and in contact with said key bars, the cross-bars of the successive stop members being preferably in contact with each other as shown at 137. By preference the ends of the stop members are curved, as shown at 138, and the key bars are of smaller thickness below than above the cross member, each key bar having a curved shoulder 139 preferably in direct contact with the upper edges of the adjoining stop members. Upon depression of any key bar, the curved shoulder 139 thereon will push the stop members 135 at the opposite sides thereof out of its path and until the key is returned to home position, none of the stop members can be shifted toward said key, so that there will be an obstruction in the path of every other key, thereby locking the remaining keys against displacement.

The zero and number 1 keys are so close together that there would not be room enough to place a stop member between them as in the case of the remaining keys. For this reason, the stop member carrier 140 is pivoted to the front plate in central position between the keys and lodged in a depression 141 therein which depression is also made to limit the movement of the stop member carrier outwardly. A rivet head 142 on the free end of the stop member carrier is in the path of the curved shoulders 138 on the zero and number 1 keys, but does not swing completely under these keys at any time, thus allowing for easy unlocking upon operation of these keys.

65 *The totalizer.*

55 The totalizer mechanism has many features in common with that of the patent to Wolfe No. 578,303 of March 2nd, 1897 and will be briefly described here. The details of this mechanism appear in various figures and particularly in Figs. 5, 10, 15, 16 and 17. The totalizer carriage 54 including the set of number wheels 50, loosely revolvable around the sleeve 54' which slides freely on shaft 51 and is held firmly in the side of carriage 54, and the set of totalizer driving idler

gears 52 loosely revolvable around the sleeve 156 which slides freely on shaft 53 and is also held rigidly in the side of carriage 54 is, as heretofore noted, shiftable by the tabulator mechanism to the position corresponding to the number of digits in the number to be added. It can be seen that the construction of short tubes rigidly held in the sides of the sliding carriage provides a very stiff mechanism independent of the comparatively long and slender shafts and acts to prevent springing of the latter.

70 Each number wheel has a ten tooth gear 151 upon its right face and at its left a Geneva locking disk 152 formed integrally with a hub 153 having a single tooth 154 aligned with the notch 155 in the locking disk 152. The totalizer driving idler set comprises a sleeve 156 on shaft 53. Upon the sleeve are mounted a set of identical members A and a set of identical members B alternating with each other. Each member A comprises a gear 157 meshing with number wheel gear 151 and a hub 158 integral therewith. Each member B comprises a Geneva 90 star wheel 159 in the plane of the notched Geneva locking disk 152 of the associated number wheel and a gear 160 integral therewith in the plane of the associated single tooth 154. The successive members A and B are in contact with each other as shown.

Upon sleeve 39 carrying the master wheel 37 is mounted a succession of carrying idlers 161. Each said idler has teeth meshing at all times with gear 157 on the adjacent member A of the totalizer idlers and with the contiguous gear 160 on member B. In the specific embodiment, the carrying idlers and the totalizer driving idlers are each provided with nine teeth, but it will be understood that they may have any other number of teeth.

75 Assuming that the carriage has been shifted to the position shown in Figs. 15, 16 and 17 for addition of a number of three digits, the master wheel 37 now meshes with the totalizer driving idler gear 157³ on the sleeve 156 (Fig. 15) and this gear in turn meshes with gear 151³ integral with the number wheel 50³ in Fig. 17. As the adding key is depressed the master wheel rotates and will rotate the number wheel gear 151³ through gear 157³, advancing the number wheel to add the digit corresponding to the adding key depressed. As the number 9 on the number wheel 151³ is reached, the single tooth 154³ comes into engagement between teeth of the corresponding totalizer carrying idler gear 160³ of member B³, and the said idler gear is, thereby, rotated through the width of one tooth. The carrying idler 161' meshing with gear 160³ rotates through one tooth and since it also meshes with gear 157⁴, the latter is rotated through one tooth, and consequently advances gear 151⁴ on num-

her wheel 50¹ through one tooth, thus performing the carrying operation.

Excessive or overthrowing movement is prevented during this carrying operation, as the Geneva star wheel 159³ which was unlocked by the presentation of the unlocking notch in Geneva disk 152³ simultaneously with the presentation of the single carrying tooth 154³ will now act to bind against the periphery of the disk 152³ as soon as the tooth 154³ has performed its advance. The carrying action proceeds in similar manner for each of the decimal places.

The teeth of the carrying idlers are beveled at their opposite sides as shown at 162 and 163 to expedite the shifting of the sets of gears 157 and 160 which mesh therewith, both in setting the carriage into tabulating position and in the step by step automatic return movement. The carrying idler units which are in mesh with gears on the carriage are as will be apparent always kept in alignment. Those carrying idlers at any time to the left of the carriage are kept in proper alignment for ready entry into mesh by means of a bar 164 riveted as at 165 to the carriage frame and extending between two teeth of the idler gears to the left of the carriage. Thus, the carrying idlers will readily enter into mesh with the totalizer idlers as the carriage moves toward the left after each key depression. A small rod 166 extends from the stationary shaft 53 and has a free left end 167 substantially in the plane of the outer surface of the master wheel for the purpose of keeping in alignment those gears of the totalizer idler group which may at any instant be to the right of the carrying idler set as shown in Fig. 15.

As the carrying idler gear 161 in immediate contact with the master wheel 37 tends to be carried along by friction in view of the fact that the master wheel is rotated for every depression of a digit key, a pawl 168 similar to pawl 112 heretofore described but preferably somewhat wider to correspond to the width of the gear is normally urged between two of the teeth thereof, thereby preventing undesired movement.

Each element of the totalizer and the totalizer as a whole, it will be seen has a type of symmetry such that it may be operated forwardly or backwardly with equal facility.

55 *Reversing mechanism.*

In view of the symmetry of the totalizer, it is merely necessary to reverse the gearing by which the same is driven in order to render possible the performance of the operation of subtraction when desired. For performing the shifting function a reversing gear 170 (see Figs. 5, 12, and 13) is preferably employed, this gear being mounted upon a stub shaft 171 fixed in end plate 23,

and being constantly in mesh with the driving gear 47 on the operating sleeve but out of mesh with countershaft gears 44 and 46. A reversing button 172 slidable upon shaft 51 preferably projects from the left end of the casing integral with a bushing 173 fitted into a corresponding hole 174 in said end and rigidly retained with respect to the shaft by means of a spring locking ring 175 adapted to drop into either of two grooves 176 located in shaft 51 for the purpose of holding the shifting mechanism steady against movement due to vibration. Locking spring 175 and the shoulder on subtraction button 172 form the limiting stops for the two positions of the subtraction button as shown in Figs. 12, 13 and 14. Integrally with the bushing is formed a shifting fork plate 177 fitting into a corresponding groove 178 in the gear hub 179 of gear 44. To perform the operation of subtraction, the operator merely presses the button inwardly to the position shown in Fig. 14, whereby the gear 46 is shifted out of mesh with the gear 47 and the gear 44 is shifted into mesh with the gear 170, so that when the operating shaft rotates, the torque is transmitted from gear 43 to gear 44 to reversing gear 170 and then to gear 47. Gear 44 is made wide enough to mesh with gear 170 before gear 46 leaves gear 47 so as to eliminate the possibility of jamming in shifting. This also does away with an intermediate or neutral position in which neither addition nor subtraction would be performed. It will be apparent that where prior to the operation of the reversing button but a single gear member 44-46 was interposed between the clutch gear 43 and the driving gear 47, two gears that is, gear 44 and reversing gear 170 are interposed in series between the clutch gear and the driving gear after it has been shifted, so that obviously, the direction of rotation of the driving gear is now the reverse of the direction above described and the totalizer will for this position of the button 172 be operated in reverse direction and will perform the operation of subtraction.

115 *Tabulation error key.*

Referring to Figs. 5, 6 and 11, there will be seen an error or spacing key 182 comprising a lug 183 fixed upon the upper surface of the casing 7, a rod 184 extending longitudinally through the said lug and terminating in a push button at its upper end, a coil spring 185 encircling said rod between said lug and said button. At its lower end, the rod contacts the tail of the tripping lever 75, so that it will be apparent that if an inaccurate tabulating setting has been made to a position of higher decimal order, it is merely necessary to depress the error key 182 in order to release the escapement ratchet 64 and allow the totalizer carriage

to space to the left step-by-step without affecting the printing mechanism.

Operation.

5 The operation of each of the elements of the machine has been set forth in connection with the description of the construction. The operation of the machine as a whole will now be summarized, the adding machine attachment being assumed secured in place upon the typewriter in the manner clearly described above and as shown in Figs. 1 and 2. For simplicity of explanation, assume that the number "30" is to be added into 10 the totalizer and printed on the paper upon the platen. The number having two places, the tens tabulator key 56 is depressed preferably with the index finger, and the thumb bar 55 is simultaneously moved toward the right with the thumb of the same hand as far as it will go, the end of the stop bar 60 then coming into contact with the stop 59 at the lower end of the tabulator key. In this action, the spring 63 is compressed and 15 the ratchet bar 64 on the carriage passes over the pawl tooth 72, the spring 63 tending to urge the carriage back after the hand is removed from the thumb bar, so that the left hand edge 67 of the ratchet tooth immediately to the right of the pawl 72 comes into contact therewith, the pawl holding the carriage in the correct position for 20 operation.

The adding key "three" is now depressed 25 through its full stroke. In this action, the tongue 22 on the key by its contact with the control plate 80 causes it to move downwardly and through the racks 85 and 86 to rotate the gears 87 and 92, which in 30 turn rotate the pinions 88 and 93 respectively, thereby rotating the loading shaft 89 to store energy in the loading spring 94 until after a definite movement, the end of the tongue 22 comes into contact with the 35 upper edge of the corresponding struck-up lug 26 on the operating plate 25, whereupon throughout the rest of the range of movement, the racks 28 on the operating plate will rotate the pinions 31 and 32 on the operating shaft 33, this rotation being imparted through the clutch gear 43 and countershaft gear 44-46 to driving gear 47 and thence through sleeve 39 to the master 40 wheel 37. The master wheel will be rotated through an angle corresponding to the number 3 and will correspondingly operate the totalizer in the manner clearly described above.

45 As soon as the operating shaft 33 starts moving, the gear 97 which is rotated therewith correspondingly rotates the gear 96 upon the loading shaft, so that the restraining effect of the loading spring is taken off the adding key, the load of the totalizer mechanism and the operating trans-

mission therefor being now substituted for that of the loading spring. During the rotation of the operating and loading shafts, the coil springs 34 and 94 store energy for returning the parts to home position in a 50 manner which will be clear below.

The lower end of the key bar 10 being directly over the key lever 4 of the number key "3" on the typewriter, the said key-lever will be depressed and the number 3 55 will be printed upon the paper on the platen of the typewriter, whereupon the typewriter escapement will advance the carriage through one space in the usual manner, independently of the mechanism of the adding machine. The front plate 17 limits the downward movement of this adding key and key bar, so that the typewriter key lever is actuated by impact, and the possibility of injury to the typewriter typebars 60 is eliminated.

65 As the control plate reaches the end of its downward stroke the tongue 110 thereon comes into engagement with the shoulder 107 on the stop-control bar 104 and the master wheel locking stop member 100 is thereby rotated about its pivot 101 to urge the point 103 thereof between two of the teeth of the master wheel 37, the locking of the master wheel occurring at the instant the control plate reaches the bottom of its stroke. Further advance of the master wheel and with it of the totalizer is thereby 70 avoided.

75 At the end of the downward stroke of the control plate, the bottom edge comes into engagement with the tail of the tripping lever 75 and the operative end thereof raises the ratchet piece 64 about its pivot 65 and out of engagement with the lower pawl 72 so that the coil spring 63 in its expansion can move the totalizer carriage through the width of one tooth toward the left, the coil spring 73 causing a return of the ratchet to its lower position, the upper stationary pawl 74 preventing movement through more than one tooth. The number wheel 50 at the extreme right is now 80 under the direct influence of the master wheel.

85 The stroke of the control plate is limited by bushings 102 which support the frame bar 102.

90 When the finger is removed from the adding key, the coiled spring 34 in its expansion will rotate the operating shaft 33 backwardly while the spring 94 will return the control plate to home position, the outer edge of the latter engaging the tongue 22 at the upper end of the key bar and returning the key to home position. At the same time, the pinions 31 and 32 at the ends of the operating shaft by their cooperation with the racks 28 at the ends of the 95 operating plate 25 will return the latter to 100

upper or home position. In this return movement, the clutch 40 opens to prevent reverse rotation of the master wheel 37. As the operating plate approaches the end 5 of its return movement, its notch 109 comes into engagement with the tongue 108 on the control bar for the master wheel stop and thereupon raises the tail of the latter about its pivot to shift the point 103 out 10 of engagement with the master wheel, so as to free the master wheel for rotation in response to the next key depression.

For operation of the zero key, the action takes place substantially as just described, 15 except that the tongue on the zero key bar first coacts with the end 121 of the lever 116, 117 on the control plate rather than with the control plate itself. The control plate is not actuated until the tongue reaches 20 the bottom of notch 118 and said plate, therefore, moves through a range somewhat less than for the digit keys and will not come into engagement with the shoulder 107 on the master control locking bar, so that 25 the master wheel will not be locked. The lug 122 on the lever 116, however, actuates the tripping lever 75 for the totalizer escapement in the manner above described, but the totalizer carriage does not move further 30 to the left than the units actuating position, so the escapement ratchet bar is lifted and then drops back into position again. The typewriter key-lever is actuated by the key bar to cause printing of the zero followed 35 by actuation of the typewriter escapement in the same manner as for the other keys.

Since the master wheel locking member remains in operative or locked condition 40 between two teeth of the master wheel throughout the return stroke for any numeral key other than zero, it is apparent 45 that it will be impossible to effectively depress the key a second time while it is on its return movement, for, the master wheel cannot be turned to actuate the totalizer until the operating plate disengages the lock, which does not occur until the extreme 50 upper end of its stroke.

After depression of any key is initiated, 55 it is necessary to move the key through its full stroke and thus record its full numerical value, since the pawl plate 127 locks the ratchet 125 upon the key bar, preventing 60 return movement. The only way to release the key is to depress it to the extreme end of its stroke, whereupon the full stroke pieces 131 and 131' are pushed by the lower end of the control plate to raise the pawl plate and thereby allow the key bar and key to return.

65 It will be apparent that when any key is partially or wholly depressed, the two-key mechanism by operation above described prevents movement of any of the other keys until the first key has reached its home or top position again.

In this manner one tabulator button setting is made for each item to be added and the adding keys will be actuated in the succession of the digits of the number, thereby printing the number on the platen, and causing corresponding advance of the totalizer, the sum being at all times read through openings 8 in the casing 7.

The sum registered by the totalizer can be printed upon the paper and the totalizer cleared concurrently therewith by pushing the subtraction button 172 inwardly preparatory to printing the sum, thereby subtracting from the number registered by the totalizer, a number equal thereto from which it follows that each number wheel will register zero. It will be understood that in this subtraction operation, the tabulating mechanism will first be set for a number corresponding to the number of places in the sum registered. By this action, it is seen that the carriage will be moved to the right to an extent such as to disclose only the first digit of the number appearing therein. When the adding key corresponding to said digit is now depressed, that number will be printed upon the paper in the typewriter and concurrently subtracted from the single number wheel shown so that the registration upon that number wheel will now be zero. The escapement will then cause the totalizer carriage to move automatically through one space to the left revealing the following digit which will then be subtracted and printed in the same manner. Thus, the digits will be successively cleared from the totalizer, and printed by the typewriter. A check to the accuracy of printing of the total will be furnished by the appearance of a succession of zeros in the totalizer. An ordinary process of subtraction for the purpose of finding the difference between two numbers is performed in the same way as addition, the subtraction button being in the normal adding position for the minuend and in the subtraction position shown in Fig. 14 for the subtrahend.

The adding machine being completely 115 above all of the keys of the typewriter and the entire typewriter key board being accessible, it will be seen that the typewriter can be operated in the normal manner without any interference from the adding machine attachment. Thus, when it is desired 120 to print a number without adding the same, the typewriter number keys are depressed in the usual manner and when it is desired to print and concurrently add a number the adding keys of the adding machine attachment are depressed.

125 It will thus be seen that we have provided a two-purpose machine, including a listing-adding machine and a typewriter susceptible of operation in the usual manner without 130 interference with touch, speed or quality of

work. The machine requires no special printed forms; can make vertical or cross additions as desired and can be used to print anywhere on the sheet, to add dollars, 5 weights, quantities or any other units. Moreover, the numbers can be punctuated or written in a continuous solid block as desired, and any number of carbons can be made in one operation.

10 The computing mechanism permits direct unimpeded operation of the typewriter at all times even when the tabulator is set.

It will also be apparent that our adding attachment does not increase the overall dimensions of the typewriter when in place thereon, so that the combined typewriter and adding attachment may be installed on the ordinary "drop-head" type of desk without chopping away or otherwise altering the latter in any particular, and the desk may be closed to conceal the machine in the usual manner. When once our adding attachment is placed on a typewriter, there is no occasion to remove it, since it interferes in no manner with the normal operation of the typewriter machine. No adjustments of the attachment of any kind are required to prepare it for operation.

It will be seen that although we prefer to employ our adding attachment in combination and in cooperation with a typewriter and in the manner set forth, the same can be used independently of any typewriter or printing mechanism. If the adding attachment shown in Fig. 2 were mounted upon any desired support, the complete adding and subtracting operations would be performed by the depression of the keys in the manner heretofore set forth, in which event the totalizer would give sums or differences depending upon the position of the reversing button, the printing of the numbers being, however, omitted. It will also be apparent that our adding mechanism might be used 45 with printing mechanisms other than typewriters although as above noted, we prefer to use it in the specific manner shown and described.

It will, of course, be apparent that many 50 changes may be made in the elements and in the various combinations thereof, all within the scope of our invention as defined in the following claims.

The control plate, for instance, in the specific preferred embodiment shown performs 55 five functions: It operates the loading means at the beginning of its stroke. It operates the master wheel stop through the stop control bar at the end of its stroke. It operates 60 the escapement lever for the totalizer carriage at the end of its stroke. It carries a special device for operating the escapement without actuating the master wheel lock when the zero key is actuated. It operates 65 the full stroke piece at the end of its stroke.

for releasing the pawl plate as each adding key is depressed to its limit. Obviously, two or more separate and distinct elements might be used for performing these various functions but we prefer to use the specific construction shown and described.

We claim:

1. In a combined typewriter and adding machine, in combination, a typewriter having a set of number keys, each provided with a key lever, a totalizer carried by said typewriter above said keys, a succession of adding key members, each having a portion directly above the lever of the corresponding number key, and adding mechanism connecting said adding keys to said totalizer, whereby said typewriter number keys may be operated without actuating said totalizer and actuation of said adding keys will cause concurrent operation of said typing keys and of said totalizer, to concurrently print and add the number.

2. In combination, a typewriter having a set of number keys, each having a corresponding key-lever, an adding machine attachment carried by said typewriter and having a set of adding keys, said levers being in the path of said adding machine keys, totalizer mechanism forming a part of said attachment, means connecting said adding keys to operate said totalizer, and means forming a part of said attachment to return said attachment keys to home position after each operation.

3. In combination, a typewriter of the type having a set of number keys with key-levers extending rearwardly therefrom, an adding machine attachment carried by said typewriter and having a set of adding key members corresponding one to each number key, said adding key members having a continuous lower edge directly above and extending at right angles to the length of the key-lever of the corresponding number key, whereby upon depression of any adding key, the corresponding key lever will be depressed to print the corresponding number; a totalizer mechanism forming a part of said attachment, and means operatively connecting the adding key to said totalizer mechanism.

4. In a combined typewriter and adding machine, in combination, a typewriter including a set of number keys from 2 to 9 inclusive in the fourth row of keys and an L-key serving as the number 1 in the second row of keys, each said key having a key-lever associated therewith, an adding machine attachment secured with respect to the typewriter and comprising a set of adding keys from 1 to 9 inclusive, each of said adding keys having a key bar, said key bars all disposed in a single plane, guides for said key bars to cause them to move lengthwise, the lower edges of said key bars being each directly above the key-lever of the cor-

responding typewriter number key, and a totalizer carried by said attachment and operatively connected to said adding keys, whereby upon depression of an adding key 6 the corresponding typewriter number key will be actuated to print the corresponding digit upon the platen and the totalizer of the adding attachment will be actuated to a corresponding extent, the bar of said number 10 1 adding key having its lower edge at an elevation somewhat higher than the lower edge of the remaining keys to compensate for the greater length of forward arm of the key-lever corresponding to the L-key 15 of the typewriter as compared to that of the number keys.

5. In combination, a typewriter of the type including a frame, and a set of number keys, each having an associated key-lever, 20 an adding attachment carried by said typewriter and comprising a base plate mounted against said frame and secured in place with respect thereto, said adding attachment including a plurality of adding key members, 25 each having in the path of its operating movement, the lever of the typewriter key of corresponding number value, said attachment including a complete adding mechanism.

30 6. In a combined typewriter and computing machine, in combination, a typewriter having a frame, number keys each controlling a key-lever, a name plate perforated at its sides for screws to secure it to the frame, 35 a computing attachment having a base plate resting against said name plate, and screws extending through said base plate, through the perforations in said name plate and into the frame of the typewriter to secure said 40 parts in assembled relation, said adding machine attachment having a series of digit key members disposed with the levers of the typewriter keys of corresponding number value in their path, said attachment including a casing, mechanism in said casing, and 45 openings in said casing through which the result of the arithmetical operations performed by the attachment may be read.

7. A combined typewriter and adding machine comprising in combination, a typewriter having a name plate, an adding machine attachment having a base plate resting against said name plate and secured with respect thereto, adding keys having bars 50 guided with respect to said base plate for up and down movement, said keys extending forwardly from said base plate and adding mechanism carried by said base plate above said keys and tapering inwardly toward said 55 base plate to leave knuckle clearance for ready operation of said adding keys.

8. In combination, a typewriter having a name plate, an adding machine having a base plate secured to said name plate, adding 60 key bars slidable in vertical grooves in said

base plate, each said key bar having a forwardly extending bracket member rigid therewith and a corresponding adding number key at the forward end of said bracket member, said attachment including a casing 70 for the adding mechanism secured to the upper end of said base plate, the lower end of said casing extending into proximity of said brackets, the front wall of said casing sloping downwardly toward said base plate 75 to leave knuckle clearance for operation of said adding keys.

9. In a typewriter of the type having a key board comprising four rows of keys with corresponding levers extending rearwardly 80 therefrom, the fourth row of said keys including the numerals 2 to 9 and zero, and the second row including the letter L serving as the numeral 1, the said typewriter including a face plate having a pair of screw holes 85 near its sides for screws to attach it to the frame; the combination therewith of an adding machine attachment having a base plate overlapping said holes in said face plate, a pair of screws passing through said holes 90 for securing said face plate and said base plate to said frame, a plurality of adding key bars guided in vertical paths by said base plate, each extending directly over the lever of the corresponding typewriter key, 95 said key bars having each a forwardly extending portion rigid therewith and number keys carried by said latter portions, said number keys normally lying in the same plane, the key bar of the number 1 key being shorter than the remaining key bars to compensate for the greater lever arm of the corresponding typewriter key-lever arm, a casing carried by said base plate and extending above said adding keys, adding 100 mechanism in said casing including a totalizer operatively connected to said adding keys, said casing tapering downwardly toward said base plate and having its lowermost edge in proximity to the forwardly extending portions of said key bars, whereby sufficient knuckle clearance will be provided for convenient operation of said adding keys, and typing keys.

10. In a computing machine, in combination, a plurality of slidable number keys, an operating plate substantially parallel to the plane of said keys, a member for registering the result of an arithmetical operation performed by operation of said keys, a mechanical connection between said operating plate and said registering member, a stop member on each of said keys and a plurality of stop members on said operating plate, one of said latter stop members corresponding to and being arranged in the path of the stop member of each of said keys, one set of said stop members being at elevations proportional to the corresponding number keys, 115 whereby the displacement of the operating 120 plate will move the stop members to and from the path of the stop member of each of the keys, and the result of the arithmetical operation will be registered by the member for registering the result of the arithmetical operation. 125

plate will be substantially proportional to the value of the number key actuated.

11. In an adding machine, in combination, a plurality of adding keys, each provided with a key bar, said key bars being disposed in a common plane, an operating plate parallel to the plane of said key bars and disposed adjacent thereto, said operating plate having stop portions, one corresponding to each said key bar, said stop portions being in stepped relation, said key bars having corresponding tongues normally aligned with each other, each having in its path the corresponding one of said stop portions, whereby, upon depression of an adding key, the operating plate will be displaced through a path proportional to the number value of the key, registering means and gear means connecting said operating plate thereto, to cause registration thereof corresponding to the displacement of the operating plate and to the number value of the key.

12. In a computing machine, in combination, a succession of number keys, each key having a key bar arranged for displacement together therewith, an operating plate extending substantially the width of all of said number keys, racks near opposite ends of said operating plate and an operating shaft journaled in said casing and provided with pinions meshing with said racks, registering means for indicating the result of the arithmetical operation performed, said latter means being under control of said operating shaft, and connecting means between said keybars and said operating plate to cause displacement of the latter through a range proportional to the number value of the key actuated.

13. In a computing machine, in combination, a plurality of number keys, each having a key bar, said key bars extending above said keys and in a common vertical plane, a casing above said keys, an operating member within said casing and extending across all of said key bars, stops on said key bars, a plurality of stops on said operating member, each said latter stop being in the path of a corresponding key bar stop, said stops being arranged with respect to each other to cause a deflection of said operating member through a range proportional to the number value of the key depressed, an operating shaft journaled in said casing, a gear connection between said operating member and said shaft, means controlled by said operating shaft for registering the results of the computations performed, and a single means for the automatic return of the depressed key and the operating member to home position after each operation.

14. In a computing machine, in combination, a plurality of exposed number keys, a casing, a totalizer therein, an operating shaft

journaled in said casing for actuating said totalizer, an operating plate slidably arranged in said casing and having a rack and pinion connection with said operating shaft at both ends, means connecting said keys to said operating plate to displace the latter through a range proportional to the number value of the key actuated, and a coil spring encircling said operating shaft and secured thereto at one end and to a point external thereof at another, whereby after operation of a key, said coil spring will rotate the operating shaft and through the rack and pinion will return the operating plate and the number key to home position.

15. In an adding machine, in combination, a casing having a base plate, a pair of side plates and a cover plate, a totalizer visible through said cover plate, adding keys outside of said casing, key bars connected to said adding keys, guided along said base plate and extending into said casing, said keys having a uniform stroke, and totalizer operating means in said casing having a lost motion connection with respect to said keys, the amount of said lost motion varying in an inverse ratio with the number of values of the keys, whereby said operating means will be actuated at a point in the key stroke such as to provide an effective totalizer actuating stroke directly proportional to the number value of the key to produce a corresponding actuation of the totalizer.

16. In an adding machine, in combination, a base plate, a casing, a plurality of number keys below said casing, each having a key bar slideable along said base plate, each said key bar having a tongue at its upper end, said tongues normally lying in the same plane, an operating plate within said casing having stops, one in the path of each said tongue, said stops being in stepped relation, whereby upon depression of a key, the tongue thereon will move freely until it engages the stop and whereby through the rest of the range of the key, the operating plate will be moved, thereby to bring about a displacement of the operating plate directly proportional to the number value of the key.

17. The combination set forth in claim 16 in which an operating shaft is journaled within said casing and has a rack and pinion connection at both ends with said operating plate for actuating said totalizer, and in which said shaft has a torsion spring coiled thereabout to return the parts to home position after each operation.

18. In an adding machine, in combination, a casing, an operating shaft therein, adding keys accessible from the exterior of said casing and connected to said operating shaft to rotate the same through an angle proportional to the number value, a gear upon said shaft having a dog clutch connection there-

- with a sleeve upon said shaft having a driving gear and a master wheel rigid therewith, a countershaft establishing a gear connection between said clutch gear and said driving gear and compression spring means to urge the clutch to closed position, whereby said clutch will transmit torque from said operating shaft through said countershaft to said sleeve and said master wheel while said operating shaft is rotating in one direction and whereby, during the rotation of said operating shaft in the other direction, said clutch will overrun against the compression of said spring to prevent displacement of said master wheel in reverse direction.
19. In a computing machine, in combination, a casing, a plurality of computing keys accessible from the exterior thereof, an operating plate extending substantially the width of said casing and arranged with respect to said keys to be displaced thereby through a range proportional to the number value thereof, an operating shaft journaled in said casing and having a rack and pinion connection with one end of said operating plate, a master wheel sleeved upon said operating shaft for operating the totalizer, spring means for returning said operating shaft, said operating plate and said keys to home position after each operation, and a one-way clutch connection between said operating shaft and said master wheel to prevent reverse operation of said totalizer during the non-operating rotation of the shaft.
20. In an adding machine, in combination, a number wheel carriage, a set of keys for operating the same, and shifting means for displacing said carriage preparatory to the registering of each digit after the first of a number of more than one digit, said shifting means comprising a ratchet bar pivoted with respect to said carriage, a stationary tooth restraining said bar against displacement, means for moving said ratchet about its pivot at the end of the operating stroke of each key, and means to rapidly return said ratchet so that its succeeding tooth is restrained by said stationary tooth.
21. In an adding machine, in combination, a number wheel carriage, a set of adding keys for operating the same, and shifting means for displacing said carriage preparatory to the registering of each digit after the first of a number of more than one digit, a ratchet bar pivoted with respect to said carriage and having teeth at opposite edges thereof, pawls for coaction with said ratchet bar, a coil spring to urge said ratchet downwardly to be arrested by the lower of said pawls and to be out of engagement with the upper thereof, and a lever actuated prior to depression of any key after the first, for raising said ratchet bar about its pivot out of engagement with said lower stationary pawl to permit the first said means to shift 65 said carriage, said upper stationary pawl acting to prevent shifting through more than one tooth.
22. In an adding machine, in combination, a pair of parallel shafts, a set of totalizer gears carried by one of said shafts, a set of totalizer idler gears carried by the other thereof, a carriage in which both said totalizer and said idler gears are mounted, a compression spring coiled about one of said shafts to urge said carriage in one direction, a ratchet pivoted to said carriage, pawl means cooperating with said ratchet to restrain said carriage against displacement by said spring, means operable by the depression of any key of said mechanism to release said ratchet from its pawl, and means to assure arresting of the next tooth of said ratchet by said pawl after each releasing action, for preventing displacement of the carriage through more than one tooth at a time.
23. In an adding machine, in combination, a set of number keys, a master wheel, operating means connecting the former to the latter to cause rotation thereof through an angle proportional to the number value of the key operated, locking means for arresting said master wheel against rotation at the end of the operative movement of said operating means to prevent advance of said number wheel by inertia, and means to unlock said master wheel at the end of the return movement of said operating means.
24. In an adding machine, in combination, a set of number keys, a master wheel, reciprocating operating means including a portion movable in the direction of movement of said keys to cause rotation of said master wheel through an angle proportional to the number value of the key operated, stop means cooperating with said master wheel to prevent rotation thereof, said stop means being in the path of said reciprocating means to be rendered operative at the end of the operating stroke and to be rendered 100 inoperative at the end of the return stroke.
25. In an adding machine, in combination, a set of adding keys, a master wheel, a stop pawl pivoted adjacent said master wheel and in a plane at right angles thereto, and means to urge said pawl into operative coaction with said number wheel at the end of the operating stroke of a key, and to return said pawl to inoperative condition at the end of the return stroke thereof.
26. In an adding machine, in combination, a totalizer operating master wheel, a set of adding keys, operating means including a plate movable with said keys, a stop pawl for said master wheel normally in inactive position, said plate being arranged to actuate said pawl at the end of its stroke to prevent 115 advance of said master wheel by inertia.

27. In an adding machine, in combination, a set of adding keys, a master wheel, operating means interposed between said keys and said wheel, a locking pawl in a plane at right angles to said master wheel, and means to bring the same into locking engagement with said master wheel for preventing excess inertia movement thereof, said operating means including an operating plate and means connecting said pawl to said operating plate to bring said pawl out of engagement with said master wheel when said operating plate reaches the end of its return movement.
28. In an adding machine, in combination, a plurality of adding keys, a master wheel, operating means including a control plate and a key operated plate in parallel relation, a stop pawl at right angles to said master wheel for coaction therewith to prevent advance thereof by inertia, said pawl having a pivot and a tail beyond said pivot, a control bar for said pawl extending through said tail and having a shoulder in the path of the advance end of said control plate, said control bar having a second shoulder in the path of the return movement of said key operated plate.
29. In a computing machine of the type comprising a set of number keys, a totalizer and mechanism operatively interposed between said keys and said totalizer to be actuated by externally applied force to an extent proportional to the number value of the actuated key, the combination therewith of means to substantially equalize the amount of work to be performed for the actuation of each key, whereby the effects of inertia in the operation of keys of lower denomination will be eliminated.
30. In an adding machine of the type comprising a set of number keys, a totalizer, an operating means interposed between said keys and said totalizer and in which the amount of work to be performed for an operation varies substantially in direct proportion with the number value of the key, the combination therewith of auxiliary load means arranged to resist actuation of the keys to an extent varying in an inverse ratio with the number value of the key in order to equalize the amount of work to be performed for the actuation of the keys.
31. In an adding machine of the type comprising a set of number keys, a totalizer, an operating means interposed between said keys and said totalizer and in which the amount of work to be performed for an operation varies substantially in direct proportion with the number value of a key having the highest value for the number 9 key; the combination therewith of auxiliary load means arranged to resist each of the keys of number value less than 9 to an extent varying in an inverse ratio with the number value thereof and to a degree to equalize the amount of work to be performed by the actuation of each key with that required for the actuation of the number 9 key.
32. In an adding machine of the type comprising a set of adding keys from 1 to 9, a totalizer, an operating means interposed between said keys and said totalizer and arranged to be actuated by said keys during a portion of the stroke thereof, substantially directly proportional to the number value of the key, the combination therewith of loading means constructed and arranged to resist movement of the keys during the idle portion of the operative stroke.
33. In an adding machine, in combination, a set of adding keys, a totalizer, operating means connecting said keys to said totalizer, and auxiliary spring means arranged to resist movement of said keys to an extent varying in an inverse ratio with the number values thereof, whereby the inertia gathered by the operation of the keys will be substantially equal.
34. In an adding machine, in combination, a set of adding keys, a totalizer, operating means interposed between said keys and said totalizer and arranged to be actuated for a fraction of the operative stroke of each key directly proportional to the number value thereof, and spring loading means for each key constructed and arranged to resist movement thereof for a fraction of the operative stroke thereof varying in an inverse ratio with the number value of said key, whereby the amount of inertia gathered by the operation of all of the keys will be substantially equal.
35. In an adding machine, in combination, a set of adding keys, a totalizer, operating means interposed between said keys and said totalizer and arranged to be actuated for a fraction of the operative stroke of each key directly proportional to the number value thereof, and spring loading means arranged to resist displacement of each key during the idle portion of the operative stroke thereof, whereby the amount of inertia gathered by the operation of all of the keys will be substantially equal.
36. In an adding machine, in combination, a set of adding keys, a totalizer, operating means interposed between said keys and said totalizer and arranged to be actuated during the final portion of the operative stroke of each key and through a range directly proportional to the number value thereof, loading means opposing displacement of said keys during the beginning of the stroke thereof, and means to remove the resisting effect of said load upon commencement of the operative portion of the key stroke.
37. In an adding machine, in combina-

tion, a set of adding keys, adding mechanism under control thereof and arranged to be actuated for a fraction of the operative stroke of each key directly proportional to the number value thereof, a torsion loading spring having one end connected to be rotated throughout the operative stroke of each key and having the opposite end normally held against rotation, and means operated at the commencement of the operative portion of the operative stroke of each key to prevent further relative movement between the ends of said spring, whereby each key will be loaded during the idle portion of its operative stroke and the load of the adding mechanism will be substituted for that of said spring during the operative portion of the stroke, thereby equalizing the inertia gathered by the operation of the keys.

38. In an adding machine, in combination, a set of adding keys, a totalizer, adding mechanism operatively disposed between said keys and said totalizer, said mechanism including a first element continuously movable throughout the operating stroke of each of said keys, a second member connected to be displaced continuously throughout the adding mechanism operating portion only of the stroke of each key, a single loading means operatively connected to each key at the beginning of its stroke, and means connecting said loading means to said second member to remove the loading effect upon commencement of the movement of said second member, whereby the amount of inertia gathered by the operation of all of the keys will be substantially equal.

39. In an adding machine, in combination, a set of adding keys, a totalizer, adding mechanism operatively disposed between said keys and said totalizer, said mechanism including a first element continuously movable throughout the operating stroke of each of said keys, a second member connected to be displaced continuously throughout the adding mechanism operating portion only of the stroke of each key, a torsion spring operatively connected to have one end wound by said first member and the other restrained against displacement by said second member, the connection between said second member and said spring being constructed and arranged to release the latter end of said spring when operation of said second member begins.

40. In an adding machine, in combination, a set of adding keys, a casing, a totalizer in said casing, mechanism connecting said keys to said totalizer to operate the latter from the former, said mechanism including a control member movable throughout the operating stroke of each adding key, a loading shaft having a torsion spring coiled thereabout and secured thereto at one end,

means for restraining the opposite end of said torsion spring against displacement, an operating shaft, means rotating said operating shaft during the mechanism actuating portion of the operating stroke, and means actuated by said operating shaft at the beginning of its rotation for releasing the restrained end of said torsion spring, whereby each of the keys will be loaded for the idle portion of its operating stroke.

41. The combination set forth in claim 40 in which the operating shaft has a gear fixed thereon and the loading shaft a gear floating thereon, one end of said torsion spring being secured to said floating gear, said floating gear having a sector of substantially the outside untoothed diameter of said gear, whereby said loading shaft will be prevented from rotating said operating shaft backwardly.

42. In a combined typewriter and computing machine, in combination, a set of typewriter number key-levers, a set of computing keys, each arranged to cause actuation of the corresponding key-lever for printing the digit upon operation of any of said computing keys, and means for substantially equalizing the work to be performed in the operation of each of said keys, whereby the keys corresponding to the lower numbers will be depressed no more quickly in normal operation than those corresponding to the higher digits and the typewriter key-levers for the lower digits will gather no more inertia than those for the higher.

43. In a combined typewriter and adding machine, in combination, a set of typewriter key-levers, a set of number keys arranged to cause actuation of the corresponding key-lever for printing the corresponding digit upon operation of any of said keys, a totalizer, adding mechanism interposed between said keys and said totalizer, loading means normally connected to the resist depression of said keys, and means removing the operative effect of said loading means when said keys come into operative connection with said adding mechanism.

44. In an adding machine, in combination, a casing, a carriage movable in said casing, tabulating means to set said carriage in a position corresponding to the number of digits of the number to be added, said means comprising a plurality of tabulator keys, one corresponding to each multiple of ten, each said key upon manual actuation thereof serving as a stop means to correspondingly limit the position of the carriage.

45. In an adding machine, in combination, a casing, a carriage movable in said casing, a group of tabulating keys for setting said carriage in a position corresponding to the number of digits of a number to be added, said keys being at the top of said casing, each said key having an associated stop in

- the casing; a shifting piece projecting from said carriage through the top of said casing and near said tabulating keys, a stop member movable with said carriage and into contact with the stop of any said key when depressed, each said tabulating key having spring means to restore it and its stop to home position, whereby a setting of said carriage may be made by depressing with 5 one finger the key corresponding to the number of digits of the number to be added, and drawing the shifting lever with the thumb until the stop thereon is arrested by the tabulator stop.
- 15 46. In an adding machine, in combination, a base plate, a plurality of adding keys, each having a key bar guided to reciprocate therealong, a casing carried by said base plate, a totalizer therein, adding mechanism 20 in said casing operatively interposed between said keys and said totalizer, each of said key bars having ratchet teeth thereon, a pawl plate urged against said key bars to lock any partially depressed key against 25 return movement and a tripping bar for said pawl plate connected to release the same from said ratchet when the extreme end of the operating stroke is reached.
47. The combination set forth in claim 46 30 in which the tripping bar has a shoulder, the said adding mechanism including a control member operatively connected to each said key to move downwardly therewith and to urge said shoulder downwardly near the 35 end of the operating stroke for effecting the tripping function.
48. In an adding machine, in combination, a base plate, a set of adding keys, each having a key bar guided to reciprocate along 40 said plate, displaceable stop pieces substantially in the plane of said key bars, each said key bar carrying an element reciprocating therewith to engage and deflect the stop means in its path when depressed, thereby 45 urging the stop means corresponding to the remaining keys into obstructing position to prevent deflection thereof until said depressed key returns to home position.
49. In an adding machine, in combination, 50 a base plate, a set of adding keys, each having a key bar guided to reciprocate along said plate, a plurality of cam-shaped pieces pivoted with respect to said base plate and between said key bars, said pivoted pieces 55 having sides overlapping said bars, each key bar having a cam conformation, whereby upon depression of any key, the pivoted pieces to each side thereof will be pushed aside to allow the key to be depressed and 60 whereby while one key is wholly or partly depressed each of the remaining keys will be obstructed by a corresponding pivoted piece.
50. In an adding machine attachment, in combination, a base plate to be mounted 65 upon the face plate of a typewriter, adding key bars guided for reciprocating movement in a vertical path along said base plate, forwardly extending arms rigid with said key bars and intermediate the ends thereof, number keys carried at the forward end 70 of said arms, a casing secured to said base plate above said arms, the upper ends of said key bars extending into said casing, adding mechanism within said casing operatively connected with said key bars, a totalizer in 75 said casing having number wheels visible through corresponding openings therein, tabulating keys upon said casing, a shifting lever adjacent said keys for setting said totalizer for the desired number of places, 80 means for automatically shifting said totalizer through the width of a number wheel after each key actuation, a member projecting from said casing for setting said mechanism for subtraction, and an error key projecting from said casing to cause return of 85 said totalizer to home position independently of key operation.
51. In an adding machine, in combination, 90 operating means, a totalizer, a master wheel under control of said operating means for actuating said totalizer, a one-way clutch in said operating means to permit return thereof without reverse rotation of said master wheel, and a stop pawl for coaction 95 with said master wheel to prevent rotation thereof beyond the correct position for any operation, said pawl being controlled by said operating means to enter into locking position at the extreme end of the operating 100 stroke, and to be returned to inoperative position at the extreme end of the return stroke.
52. In an adding machine, in combination, 105 a set of number keys, an operating plate controlled thereby to be displaced by each key through a range proportional to the number value thereof, an operating shaft having a rack and pinion connection with 110 said plate, a master wheel for controlling a totalizer, said master wheel being sleeved upon said shaft, a clutch connection between said pinion and said master wheel, a locking pawl for cooperation with said master wheel, a control plate arranged to be moved by the operation of each said key and to actuate said pawl at the end of the 115 operation of said wheel, and a member connected to said pawl to be engaged by said operating plate in the return path thereof for releasing said pawl when said operating plate approaches the extreme end of its return stroke.
53. In an adding machine, in combination, 120 a plurality of adding keys, a totalizer, operating means connecting said keys to said totalizer, said operating means including an operating shaft, a master wheel freely 125

- mounted upon said shaft to control said totalizer, a coil spring to return said operating shaft after each operation, a one-way clutch drivingly connecting said master wheel to said shaft to prevent reverse rotation of said master wheel during the return movement of said shaft, tabulating means for setting the position of said carriage in accordance with the number of digits of the number to be recorded, a compression spring to urge said carriage toward the left, pawl and ratchet means for restraining said carriage against return, said operating means including a control member to release said pawl and ratchet with respect to each other between each operating stroke and the next to permit advance of the carriage through the width of one ratchet tooth.
54. In an adding machine, in combination, a set of adding keys, a totalizer having a series of number wheels, a master wheel for actuating said totalizer, operating means connecting said keys to said master wheel to rotate the latter through an angle proportional to the number value of the key, a locking member for said master wheel, and means for successively operating said locking member at the end of every advance of said wheel, and causing the advance of said totalizer through the width of one number wheel, said operating means being arranged to release said locking member at the end of the return movement thereof.
55. In an adding machine, in combination, a set of adding keys, a totalizer carriage having a series of number wheels, a master wheel for actuating said totalizer, operating means connecting said keys to said master wheel to cause rotation thereof upon each key operation through an angle proportional to the number value of the key, a locking stop for said master wheel, a pawl and ratchet means for governing the advance of said totalizer carriage after each key operation, and a single control plate for moving said locking pawl to locking position upon the completion of each master wheel actuation and for tripping the ratchet mechanism to effect advance of the totalizer carriage through the width of one number wheel.
56. In an adding machine, in combination, a set of adding key members, a totalizer carriage having a series of number wheels, an operating plate in the path of movement of each said key member and constructed and arranged with respect to said key members to be moved through a range proportional to the number value thereof, a master wheel for actuating said totalizer, a transmission between said operating plate and said master wheel, a locking member for coaction with said master wheel, pawl and ratchet means for governing the advance of said totalizer carriage, and a single control plate actuated by the depression of any key for bringing said locking member into operative position upon completion of each master-wheel advance and for tripping said pawl and ratchet means to cause advance of the totalizer carriage through the width of one number wheel, and means connected to said locking member and in the path of said operating plate to cause release of said locking member at the end of the return movement of said operating plate.
57. In an adding machine, in combination, a plurality of number keys from 1 to 9 and a zero key, a totalizer, a master wheel for actuating said totalizer, an operating plate under the control of said keys to be displaced thereby through a range proportional to the number value thereof, a transmission between said operating plate and said master wheel, a locking pawl for coaction with said master wheel, ratchet mechanism for bringing about advance of said totalizer after actuation of each key, a single control member for actuating said locking pawl at the completion of each operation of the master wheel and for tripping said ratchet mechanism to cause advance of the totalizer, means connected to said locking pawl and in the path of the return movement of said operating plate to trip said pawl at the end of the return movement thereof, said control member being constructed and arranged to actuate said ratchet mechanism upon the depression of each of said keys, and to actuate said locking pawl upon actuation of each of said keys, except the zero key.
58. In an adding machine, in combination, a set of adding keys, a totalizer, a master wheel for actuating said totalizer, operating means connecting said keys to said master wheel to cause rotation thereof, said operating means including a member under control of each of the keys, and constructed and arranged with respect thereto to be displaced through a range proportional to the number value thereof, there being a lost motion between said key and said operating member at the beginning of the operative stroke of the key, varying in length in an inverse relation with the number values of the keys, loading means resisting operation of the key during the lost motion portion of the stroke to prevent the accumulation of momentum and locking means under control of said operating means to restrain said master wheel against advance or return movement after the completion of each actuation thereof.
59. The combination set forth in claim 58 in which the locking means for the master wheel is connected to the operating member to be released at the end of the return stroke thereof.

60. In a totalizer mechanism of the type comprising a master wheel, a set of totalizer number wheels, a set of totalizer idler gears, a set of carrying gears coaxial with said master wheel, a spring pawl coacting with said master wheel to prevent undesired rotation thereof, and a locking pawl in a plane at right angles to said master wheel arranged to cooperate therewith to prevent movement thereof after the completion of each operation.

61. In an adding machine, in combination, ten adding keys, one for each digit and one zero key, a casing, a totalizer carriage therein having a series of number wheels, a master wheel for actuating said totalizer, an operating plate in said casing for actuating said master wheel, each key having a key bar extending into said casing, said operating plate being in the path of said key bars and being arranged with respect thereto for lost motion of said keys at the beginning of the operative stroke thereof varying in an inverse relation with the number values of the keys to cause displacement of the operating plate through a range proportional to the number value of the keys, loading means connected to resist operation of the key at the beginning of the operative stroke thereof, locking pawl means arranged to coact with said master wheel, ratchet means to effect advance of said totalizer carriage, a member for locking each key against return movement from any position intermediate the range of its displacement, and a single member for connecting said keys to said loading means at the beginning of each stroke for causing operation of said master wheel locking member at the completion of each master wheel actuation, for causing operation of said escapement after each master wheel actuation to bring about advance of said carriage through the width of one number wheel and for releasing said key locking member at the end of the key stroke to permit return of the key.

62. The combination set forth in claim 61 in which a member connected with the locking pawl is arranged in the path of return movement of the operating plate to release said pawl at the extreme end of the return movement of said operating plate.

63. The combination set forth in claim 61 in which the control member is constructed and arranged with respect to the zero key in such manner as to cause operation of said escapement and to omit actuation of said locking pawl when said zero key is depressed.

64. In an adding machine, in combination, a set of adding keys, a totalizer, a master wheel, operating means connecting said keys to said master wheel, said operating means being arranged to be actuated by each said

key through a stroke proportional to the number value thereof, a control plate connected to said keys to be moved throughout the complete range of operation thereof, a loading shaft, a rack and pinion connection between said control plate and said loading shaft, said loading shaft having a spring coiled thereabout and fixed at one end, and means to release said fixed end of said spring at the termination of the idle portion of each key stroke.

65. In an adding machine, in combination, a base plate, a plurality of adding key bars arranged to be reciprocated thereon, each having an adding key rigid therewith and a projection near its upper end, a casing mounted upon said base plate above said keys, said casing having end walls and a front wall, an operating plate in said casing having stepped projections in the path of the corresponding projections on said key bars, racks near the opposite ends of said operating plate, an operating shaft having pinions at its opposite ends meshing with said racks said operating shaft having a torsion spring coiled thereabout, a set of carrying gears and a master wheel sleeved upon said shaft, a gear transmission including a one-way clutch drivingly connecting said operating shaft to said master wheel, a series of totalizer number wheels and a series of totalizer idlers, a carriage supporting said wheels and said idlers, shaft means parallel to said operating shaft for mounting said carriage, a compression spring to urge said carriage in one direction, pawl and ratchet means for controlling the position of the carriage, a loading shaft journaled in said end walls, a control plate parallel to said operating plate and having a rack and pinion driving connection with said loading shaft, said loading shaft having a torsion spring encircling the same, and a connection between said operating shaft and said loading shaft to render said loading means inoperative upon commencement of the rotation of said operating shaft.

66. A calculating mechanism comprising a casing engaged with a typewriter, a carriage movable in said casing, a totalizer therein, means for actuating said totalizer and the numeral keys of the typewriter simultaneously means for moving said carriage, a plurality of stops limiting the carriage movement, said stops being independently operable, and an error key whereby the carriage may be returned to its initial position.

67. A calculating attachment for a typewriter comprising a casing secured to the frame of a typewriter, a totalizer in said casing, means for moving said totalizer lengthwise so as to disclose numerals carried by its wheels through apertures in said casing, keys for operating said totalizer, and

- means combined with said keys for coincidentally operating the numeral key levers of the typewriter, said means avoiding interference with the normal use of the typewriter.
68. A calculating mechanism comprising a casing, a totalizer, means for moving said totalizer lengthwise in said casing, an actuating gear engageable with any of the numeral wheels of said totalizer, a stepped plate extending from end to end of said casing, key operated means engaging the steps of said plate whereby it may be moved vertically, mechanism for transferring reciprocative movement of said plate to rotary movement of said actuating gear and equalizing means at the ends of said plate compelling it to move parallel to itself irrespective of the point where pressure is applied.
69. A combined typewriter and computing machine comprising a typing mechanism, typing key levers for operating the same, a carriage and an escapement to automatically advance the carriage after each key operation, a computing mechanism including a totalizer, and means apart from said typing mechanism including computing number key members for controlling all steps of the operation of said totalizer to perform the computing operation, said typing key levers being in the path of operation of the computing number key members, and said latter key members being out of the path of operation of the former, whereby said typing number keys may be operated without actuating said totalizer, and actuation of said computing keys will cause concurrent operation of said typing keys and of said totalizer, to concurrently print the number and introduce it into the totalizer.
70. In combination, a typewriter having a set of typing number keys, an adding machine attachment carried by said typewriter, and having a set of adding key members corresponding one to each number key, said adding key members having lower edges above the key levers of the corresponding number keys, whereby said typing number keys may be operated without actuating said adding machine attachment and actuation of said adding keys will cause concurrent operation of said typing keys and of said adding machine attachment to concurrently print and add the number.
71. In a combined typewriter and computing machine, in combination, a typewriter having a frame, a set of typing number keys, a set of key levers, one actuated by each of said keys, a front plate perforated at its sides for screws to secure it to the frame, a computing attachment having attachment ends resting against said front plate, and screws extending through said attachment ends, through the perforations in said front plate and into the frame of the typewriter to secure said parts in assembled operative relation.
72. In combination, a typewriter having a frame, a row of number keys, an adding machine having a base plate secured to said frame, adding key bars vertically slidable with respect to said base plate, each said key bar having a forwardly extending bracket member above said number keys carrying a corresponding adding number key at the forward end thereof, thereby leaving knuckle clearance for operation of the typing number keys.
73. In combination, a typewriter having a frame, a name plate secured to the front of said frame and a row of typing number key members adjacent said name plate, an adding machine attachment secured to said typewriter and having adding key members arranged with the corresponding typing number key members in their path, said adding machine attachment being constructed and arranged to allow knuckle clearance for operation of said adding keys and to allow knuckle clearance for operation of said typing number keys, whereby each of said sets of keys can be operated without impediment.
74. In combination, a typewriter having a frame and a name plate secured thereto, a row of typing number keys adjacent said name plate, each having a key lever extending rearwardly therefrom, an adding machine attachment having a base plate secured to said frame and against said name plate, adding key bars vertically slidable with respect to said base plate, each arranged with the corresponding typewriter key lever in its path, each said key bar having a forwardly extending bracket member rigid therewith and a corresponding adding number key at the forward end of said bracket member and at a higher elevation than said typing number keys, thereby leaving knuckle clearance between said adding keys and said typing number keys for operation of the latter, said attachment including a casing for the adding mechanism at the upper end of said base plate, the lower end of said casing extending into proximity of said brackets, the front wall of said casing sloping downwardly toward said base plate, thereby leaving knuckle clearance between said casing and adding keys for operation of the latter.
75. In a computing machine, in combination, a plurality of number keys, a totalizer, totalizer operating means adapted to be actuated by direct finger pressure applied to said keys, and horizontal torsional springs of an axial length many times greater than its diameter to return the keys and said totalizer operating means to home position, upon completion of the operating stroke.
76. An adding machine attachment for typewriters comprising a base plate, adding

mechanism and a set of key bars, adjacent sides of consecutive key bars being at a distance from each other less than the distance between the outer edges of successive number key levers on the make of typewriter in which said distance is a minimum and having the distance between the more remote sides of said key bars greater than the distance between adjacent sides of consecutive key levers on the make of typewriter in which said distance is a maximum, whereby said adding machine attachment can be used without special adjustment or adaptation to bring the key bars into coacting with the corresponding key levers, of various makes of typewriting machines.

77. An adding machine attachment for typewriters including a base plate, adding mechanism thereon, a set of slidable adding key bars arranged in a single plane at equal distances from each other, each said key bar having a substantial width in the plane thereof, the distance between the extreme edges of the extreme keys being greater than the distance between adjacent edges of the corresponding key levers of one form of typewriter and the distance between adjacent edges of the extreme bars being less than the distance between the outer edges of the corresponding key levers of another form of typewriter, whereby said adding attachment may be applied without special adjustment or adaptation to either of said makes of typewriters and to any other make in which the distance between the keys is intermediate between the distances in the said two makes.

78. The combination set forth in claim 77 in which the nine equidistant keys are of number value in succession from 2 to 9 and zero, and in which a tenth key bar for the number 1 key is arranged adjacent the zero key bar, said latter key bar having a position such and a width such that when the attachment is applied to any make of typewriter, said key bar will have the lever of the L-key thereof in its path of operation.

79. In a typewriter, in combination, typing key levers, actuating keys therefor, each key having the corresponding key lever in the path of operation thereof, and limit stop means for said actuating keys to prevent injury to the typewriter, which might result from the application of excessive force to the key levers, said stop means being in a position such as to ensure impact printing operation of the typewriter.

80. In apparatus of the character described, in combination, a typewriter combined with a mechanical attachment therefor, said apparatus comprising typing means including a row of number key members, said mechanical attachment having a set of corresponding typing number key members, each directly above the set of operating members,

and stationary stop means for limiting the stroke of said operating members to assure impact typing operation.

81. A combined typewriter and adding machine comprising typing mechanism including a row of number key members, an adding machine attachment having a set of key bars each directly above the corresponding typing number key member, and stationary stop means for limiting the stroke of said adding key members to assure impact typing operation.

82. An adding machine for typewriters comprising a base plate, adding mechanism thereon, a set of adding key bars slidable along said plate, stop means on each said key bar, and stationary stop means on said base plate to limit the stroke of each key bar.

83. In an adding machine attachment for typewriters, in combination, adding mechanism, a set of slidable adding key members for actuating said mechanism, means for securing said attachment to a typewriter to dispose an operating portion of each adding key member to extend above and for coaction with a portion of the corresponding typewriter number key member, means for limiting the movement of all said adding key members to a definite uniform stroke, said securing means being normally arranged for ready application to a typewriter with the operating portions of said adding keys at an elevation above the lowermost position of the typewriter number key portion with which it coacts, no less than the stroke of said adding key.

84. The adding attachment set forth in claim 83 in which each adding key member includes a key bar, the lower edge of which when the attachment is applied to the typewriter normally extends directly above the normal uppermost position of the corresponding typing number key lever portion with which it coacts.

85. The adding attachment set forth in claim 83 in which the uniform adding key stroke is longer than that of the portion of the typing number key member with which the adding key member coacts when the attachment is applied to a typewriter of a certain make, and in which the adding attachment has means for securing it to the typewriter in position such as to dispose the typing key operating portion of the adding key above the typing key member at a distance to provide lost motion substantially equal to the excess of the adding key over the typewriter key stroke length.

86. The adding attachment set forth in claim 83 in which the uniform adding key stroke is shorter than that of the portion of the typing number key member with which the adding key member coacts when the attachment is applied to a typewriter

of a certain make and in which the adding attachment has means for securing it to the typewriter in position such as to dispose the typing key operating portion of the adding key substantially in contact with the uppermost normal position of the typing key member, the excess of the typewriter over the adding key stroke length being traversed by reason of the inertia of the 10 typing number key member.

87. An adding attachment for typewriters, comprising a set of adding key bars in which the adjacent sides of successive members are spaced from each other by a distance less than that between the outer sides of the corresponding number key levers of a typewriter having a relatively narrow key board, and in which the distance between the outer sides of successive key bars is greater 15 than that between the adjacent sides of the corresponding number key bars of a typewriter having a relatively wide key board, the adding keys having a definite uniform stroke greater than that of the coacting typ- 20 ing key lever portions of some makes of typewriters, and means for readily securing said attachment to any of a plurality of typewriters of different standard makes in a position such as to provide for a lost 25 motion at the beginning of the adding key stroke prior to engagement with the typing key member substantially equal to the excess of the adding key over the typewriter key stroke length.

88. An adding attachment for typewriters, comprising a set of adding key bars in which the adjacent sides of successive members are spaced from each other by a distance less than that between the outer sides of the corresponding number key levers of a typewriter having a relatively narrow key board, and in which the distance between the outer sides of successive key bars is greater than that between the adjacent sides of the corresponding number key bars of a typewriter having a relatively wide key board, the adding keys having a definite uniform stroke intermediate in length between the longest and the shortest stroke in the case of different standard makes of typewriters, means for readily securing said attachment to any of a plurality of standard makes of typewriters in a position such as to provide for a lost motion at the beginning of the adding key stroke prior to engagement with the typing key member substantially equal to the excess of the adding key over the typewriter key stroke length, and in the case of typewriters with key strokes longer than that 55 of the adding keys to provide for substantially no lost motion connection, the final movement of the typing key member in the latter case taking place by inertia.

89. The combination set forth in claim 83 60 in which the computing attachment includes

a base plate with holes at the same distance apart as the regulation holes in the name plate of the typewriter, and in such position that when said attachment is secured to the typewriter with said holes in registry, the operating parts will be in the relative position set forth.

90. The combination set forth in claim 88 in which the computing attachment includes a base plate with holes at the same distance apart as the regulation holes in the name plate of one make of typewriter, and in such position that when said attachment is secured to said typewriter with said holes in registry, the operating parts will be in correct relative position to suit the key stroke length of said make of typewriter, and ears adapted to be secured to the ends of said base plate, said ears having apertures at the same distance apart as the regulation holes in the name plate of another make of typewriter, said apertures being in such positions as to dispose the attachment in correct relative position to suit the key stroke length of said latter make of typewriter.

91. In a computing machine, in combination, a set of computing keys, a casing having end walls, computing mechanism under control of said keys and enclosed in said casing, said mechanism including an element extending the length of said casing, said element having a rack and pinion operating connection near each end thereof, and guide means rigid with said member and slidable 100 in grooves in said end walls.

92. In a computing machine, in combination, a bank of computing keys, computing mechanism under control thereof, said mechanism including an element extending substantially the width of said key bank and under control of each said key, means to assure a substantially pure movement of translation of said element, and stop means in the path of said element to limit the stroke 110 thereof.

93. In a computing machine, in combination, a base plate, a set of computing keys slidable thereon, computing mechanism under control thereof, a casing enclosing said mechanism, said mechanism including a plate under control of each of said keys, means for assuring a pure movement of translation of said plate, a stationary frame bar within said casing, elements of said computing mechanism being mounted on said frame bar, a pair of bushings for supporting said frame bar in spaced relation with respect to said base plate, said bushings being in the path of movement of said plate, and thereby serving to limit the stroke 120 thereof.

94. A two-key mechanism for operating key bars, comprising a plate extending over 130 all said key bars and substantially in con-

tact with the surfaces thereof, stop members between said key bars, a pair of key bars in close proximity to each other, a member lodged in a depression in said plate and 5 pivoted midway between said latter key bars, each said latter key bar having a curved stop portion, said pivoted member having a projection in the path of movement of said stop portions, the width of the depression being such as to limit the deflection of said pivoted member to an extent such as to prevent jamming of the pivoted member.

95. In a ratchet rack escapement mechanism, in combination, a bar having teeth 15 on opposite edges thereof, a pair of pawls fixed with respect to each other, one for cooperation with each of said sets of teeth, the distance between said pawls being 20 such as to cause coaction between one said pawl and one of the corresponding set of teeth, when the other pawl is released with respect to the associated set of teeth, the teeth cooperating with said latter pawl 25 having inclined edges, whereby said ratchet rack bar will be restrained against advance through the width of more than one tooth.

96. In an escapement, in combination, an escapement ratchet rack bar having a succession of teeth at one edge, each of said teeth having one side perpendicular to the length of said bar and another side inclined with respect thereto, a second set of teeth at the opposite edge of said bar, the sides of 35 said second set being inclined with respect to the length of said bar, a pair of pawl teeth in fixed position with respect to each other, one normally in cooperation with one of said first group of teeth and the other 40 normally spaced from said second group of teeth, whereby upon release of said bar with respect to said first pawl, said second pawl will come into cooperation with one of said inclined teeth, thereby tending to prevent 45 advance through more than one tooth.

97. A calculating mechanism comprising a casing engaged with a typewriter, a totalizer in said casing, an escapement for said totalizer, means for rotating the wheels of said 50 totalizer, and actuating the numeral keys of the typewriter simultaneously, and means for actuating said escapement independently of the typewriter.

98. A calculating mechanism comprising 55 a casing engaged with a typewriter, a carriage movable in said casing, a totalizer in said carriage, an escapement for said carriage, means for rotating said totalizer wheels and actuating the numeral keys of the 60 typewriter simultaneously, and means for actuating said carriage escapement independently of the typewriter.

99. A calculating mechanism comprising a casing mounted upon a typewriter, a car-

riage movable in said casing, a totalizer 65 therein, numeral keys for actuating said totalizer, a unitary operating plate for the wheels of said totalizer to extend horizontally across the front of the typewriter and in a substantially vertical plane, said plate 70 having steps representing each numeral from 0 to 9, and means for moving said plate and the numeral key levers of the typewriter simultaneously and in parallel paths.

100. The combination with a key operated calculating machine having a totalizer and means for operation thereof, of a typewriter, rigid connections removably engaging between the frame of said machine and of 75 said typewriter, said calculating machine 80 having operating keys constructed and arranged to operate the numeral keys of the typewriter.

101. A calculating machine comprising a 85 casing carried by a typewriter, a totalizer operable in said casing, and keys for actuating said totalizer, said keys normally loosely resting non-interferingly above the numeral key levers of the typewriter.

102. A calculating attachment for a typewriter comprising a casing secured to the frame of a typewriter, a totalizer in said casing, keys for operating said totalizer, and means combined with said keys for coincidentally operating the numeral key levers 95 of the typewriter, said means avoiding interference with the normal use of the typewriter.

103. A calculating attachment for a typewriter comprising a casing secured to the 100 frame of the typewriter, a totalizer in said casing, means for moving said totalizer lengthwise so as to disclose numerals carried by its wheels through apertures in said casing, keys for operating said totalizer, and means combined with said keys coincidentally causing the typewriter to print the numeral 105 represented by the totalizer key depressed.

104. A calculating mechanism comprising 110 a casing, a totalizer, an actuating gear engageable with any of the numeral wheels of said totalizer, a stepped plate extending from end to end of said casing, key-operated means engaging the steps of said plate, whereby it may be moved vertically, mechanism for transferring reciprocal movement of said plate to rotary movement of said actuating gear, and equalizing means at the ends of said plate compelling it to move in a strictly translational course irrespective of the point where pressure is applied.

105. A calculating mechanism comprising 115 a casing engaged with a typewriter, a carriage movable in said casing, a totalizer in said carriage, means for rotating the wheels of said totalizer when so engaged and actuating the typewriter simultaneously so as 120 125

- to freely permit typing the figures being computed in any arrangement or with any designations.
106. A calculating mechanism engaged with a typewriter, comprising a totalizer, an independent escapement for said totalizer, transmission means for actuating said totalizer simultaneously with the typewriter, said mechanism including a keyboard for actuating said totalizer independently of and apart from the typewriter.
107. A key operated calculating mechanism engaged with a typewriter, comprising a totalizer, having numeral wheels visible from in front of the typewriter and means for engaging said calculating mechanism with the typewriter so as to permit simultaneous actuation therewith, said calculating mechanism permitting direct unimpeded operation of the typewriter at all times.
108. A calculating mechanism engaged with a typewriter and permitting unimpeded use of the typewriter at all times, a totalizer in said calculating mechanism, stepped means for numerically actuating said totalizer, and means for operating said stepped means and the numeral key levers of the typewriter simultaneously.
109. A calculating mechanism comprising a casing fixed to a typewriter, a totalizer, means for moving said totalizer, tabular stops to set said totalizer in operating position and a series of numeral keys to actuate said totalizer and the typewriter simultaneously.
110. A preassembled calculating unit mounted upon a typewriter, including a totalizer, independent escapement means for moving said totalizer, and means for operating said totalizer and the numeral keys of the typewriter simultaneously.
111. A calculating mechanism comprising a totalizer, a plurality of keyed stems, a plate engaged at spaced intervals by said stems, equalizing devices at the ends of said plate, resilient means for maintaining said plate in a raised position, a second plate having stops spaced in conformity with said key stems and contactable therewith when the stems are depressed, and means for actuating said totalizer upon depression of said stems.
112. A combined typewriter and computing machine including a computing unit having a totalizer, a tabulator for said totalizer, a bank of number keys, said machine being constructed and arranged to correctly set up in the totalizer and to print through the typewriter mechanism any number within the range of the adding mechanism, by performing a tabulator operation and then successively actuating those keys of the bank corresponding to the successive digits of the number all of the keys of the typewriter be-
- ing free for direct operation at all times regardless whether the tabulator is in set or in idle position.
113. In combination, a typewriter having a set of number key levers, a computing machine attachment carried by said typewriter and including a totalizer, a set of selective totalizer actuating members cooperating with said typewriter key levers, and means forming a part of said attachment to return the actuated operating member to home position after each operation.
114. In a combined typewriter and computing machine, in combination, a typewriter having a frame, number keys, each controlling a key lever, a computing attachment having a support structure resting against a portion of the typewriter frame, screws extending through said supporting structure and threaded into holes that are formed in regular standard typewriter frames not specially designed for computing attachments, said adding machine attachment having a series of digit key members disposed in functional operating position with respect to the typewriter keys.
115. In a computing machine, in combination, a set of ten number keys from zero to nine, a member for indicating the result of an arithmetical operation performed by operation of said keys, a single one-piece operating member operatively disposed between all of said keys and said indicating member, said number keys being disposed with respect to said operating member in such manner as to cause the latter to be actuated for each key operation to an extent proportional to the number value thereof.
116. In an adding machine, in combination, a set of adding keys, a totalizer, and a single one-piece operating member therefor arranged with respect to said adding keys for deflection proportional to the number value of the key depressed, said operating member being connected to said totalizer.
117. In a computing machine, in combination, computing keys, a totalizer, a transmission between said keys and said totalizer, including a one-piece operating plate actuated through a range proportional to the number value of the key operated, means to return the transmission and the operated key to home position after operation, and a driving connection between said transmission and said totalizer connected to advance said totalizer while the transmission is operating in one of the directions of its movement, and to an extent proportional to the range through which said operating plate was actuated.
118. In an adding machine, in combination, a plurality of number keys from 1 to 9 inclusive and a zero key, a totalizer, a master wheel for actuating said totalizer, transmis-

sion means between said keys and said master wheel to cause rotation of the latter through an angle proportional to the number value of the actuated key, said transmission means including an operating plate under the control of said keys to be displaced thereby through a range proportional to the number value thereof, and totalizer carriage advancing means connected to be operated by the depression of any key, including the zero key.

119. In a totalizer mechanism of the type comprising a master wheel, a set of totalizer number wheels, a set of totalizer idler gears, a set of carrying gears coaxial with said master wheel, said carrying gears together with said master wheel preventing undesired rotation of said idler gears and a locking pawl arranged to cooperate with said master wheel to prevent movement thereof after the completion of each operation.

120. A calculating mechanism comprising a casing engaged with a typewriter, a totalizer therein, means for actuating said totalizer and the numeral keys of the typewriter simultaneously, a plurality of stops for determining selectively the decimal setting of the totalizer, said stops being independently operable, and a back spacing key whereby the totalizer setting may be returned to units position.

121. A calculating attachment for a typewriter comprising a casing secured to the frame of a typewriter, a totalizer in said casing, means for moving said totalizer lengthwise so as to disclose numerals carried by its wheels through apertures in said casing, a set of selective totalizer actuating members cooperating with said actuating gears, and means combined with said members for coincidently operating the numeral key levers of the typewriter, said means avoiding interference with the normal use of the typewriter.

122. A calculating attachment for a typewriter comprising a casing secured to the frame of the typewriter, a totalizer in said casing, means for moving said totalizer lengthwise, an actuating gear engageable with any of the wheels of said totalizer, means for shifting the direction of rotation of said gear so that either addition or subtraction may be accomplished on said totalizer, a set of selective totalizer actuating members cooperating with said actuating gears, and means combined with said members for coincidently operating the numeral key levers of the typewriter, said means avoiding interference with the normal use of the typewriter.

123. In combination, a typewriter having a set of typing number keys, an adding machine attachment carried by said typewriter, and having a set of adding key

members corresponding one to each number key, the key levers of the corresponding number keys being independent of but extending in the path of said adding key members, whereby said typing number keys may be operated without actuating said adding machine attachment and actuation of said adding keys will cause concurrent operation of said typing keys and of said adding machine attachment to concurrently print and add the number.

124. A calculating mechanism comprising a casing carried by a typewriter, a carriage movable in said casing, a totalizer therein, and keys for actuating said totalizer, said keys normally in contact with the upper edges of the numeral key levers of the typewriter without interference with their usual functions.

125. A calculating mechanism comprising a casing, a totalizer therein, keys for actuating said totalizer, said mechanism including means for normally sustaining said keys free from contact and above the numeral key levers of the typewriter with the latter in the path of operative displacement of the keys.

126. In a combined typewriter and adding machine, the combination of a typewriter having an adding machine attachment secured with respect thereto, a complete adding key bank having keys of uniform stroke operating in a common plane, said typewriter having numeral key levers, each having a part thereof in the range of operation of the corresponding adding machine key, the portions of the typewriter key levers in the range of the adding keys having different lengths of stroke, the clearances between the adding keys and the key levers being such as to compensate for the different key lever strokes.

127. The combination of a typewriter of the type including a frame and a set of number keys, each having an associated key lever, a computing attachment carried by said typewriter, screws securing said attachment to the typewriter frame by threading into holes to accommodate screws of the regular typewriter construction, said computing attachment including a plurality of computing key members, each having in the path of its operating movement, the lever of a typewriter key of corresponding number value.

128. In a typewriting machine of the type comprising a frame having a pair of screw holes therein for attachment of a part of the typewriter construction, and number keys, each controlling a key lever, the combination therewith of a computing attachment having a frame structure carried by the typewriter frame and screws extending through said structure into said screw holes for mounting said attachment in position,

said attachment having a series of digit key members disposed with the typewriter keys of corresponding number value in their path.

129. In a computing machine of the type comprising a bank of number keys, a totalizer, mechanism operatively interposed between all of said keys and said totalizer, and means controlled by a member having a uniform movement for each key operation, to equalize the force required for operating the machine with any key.

130. In a combined typewriter and computing machine having a platen, a typing mechanism, typing numeral key levers for operating the same, a carriage and a computing mechanism including a totalizer; the combination of a tabulator mechanism distinct from the typewriter mechanism for setting the computing machine in readiness for operation thereof, numeral keys in operative relation when the computing mechanism is thus set, to simultaneously operate the typing and the computing mechanism, escapement means to automatically advance the typewriter and the computing mechanism after each operation, said typing mechanism being normally free from the load of any part of said computing mechanism to permit operation of the typing numeral key levers apart from the computing mechanism, in all positions of the typewriter platen.

131. A combined typewriter and adding machine comprising a typewriter frame, typewriter number key members, adding mechanism carried by said frame including a set of slidable adding transmitters for actuating said mechanism, each transmitter having an operating portion extending above and for coaction with a portion of the corresponding typewriter number key member, means for limiting the movement of all said adding transmitters to a definite uniform stroke, the operating portions of said adding transmitters being normally at an elevation above the lowermost position of the typewriter number key portion with which it coacts no less than the stroke of said adding transmitter.

132. The mechanism set forth in claim 131 in which each adding transmitter includes a key bar, the lower edge of which extends directly above the normal uppermost position of the corresponding typing number key portion with which it coacts.

133. The mechanism set forth in claim 131 in which the uniform adding transmitter stroke is longer than that of the portion of the typing number key member with which the adding transmitter coacts and in which the typing key operating portion of the adding transmitter is disposed above the corresponding part of the typing key member at a distance to provide lost motion substantially equal to the excess of the adding

transmitter for the typewriter key stroke length.

134. A computing attachment for a typewriter including a totalizer, said attachment being adapted to be connected in functional operating position with respect to a standard typewriter and free from interference with the normal operation of the latter at all times, by removing typewriter screws and using the corresponding screw holes for securing the attachment, and means for operating said totalizer and the numeral key levers of the typewriter simultaneously.

135. In a combined typewriter and computing machine having a platen, a single set of numeral type bars, typing numeral key levers for operating the same, a carriage and an escapement to automatically advance the carriage after each operation and a computing mechanism including a totalizer; the combination of an escapement therefor, means to set the computing machine in readiness for operation thereof and numeral keys in operative relation when the computing mechanism is thus set, to simultaneously operate the said type bars and the computing mechanism, said typing numeral key levers being free from the load of any part of said computing mechanism immediately upon complete entry of a number into the totalizer to permit operation of the typing numeral key levers apart from the computing mechanism in all positions of the typewriter platen.

136. In a combined typewriter and computing machine having a frame, a platen, a typing mechanism, typing numeral keys for operating the same, a carriage and an escapement to automatically advance the carriage after each operation; the combination of a pre-assembled computing unit mechanism immovably fixed upon said frame, including a totalizer and including means to set the computing mechanism in readiness for operation thereof, and numeral keys in operative relation when the computing mechanism is thus set to simultaneously operate the typing and the computing mechanism, said typing mechanism being normally free from the load of any part of said computing mechanism and accessible to permit operation of the numeral typing key levers apart from the computing mechanism in all positions of the typewriter platen.

137. In a combined typewriter and computing machine having a platen, a typewriter mechanism, a base therefor, typing numeral key levers for operating the mechanism, a carriage and an escapement to automatically advance the carriage after each operation; the combination of a computing mechanism sustained by the typewriter base and including a totalizer and a master wheel movable step by step relative to each other, said movement being independent of type-

- writer carriage movement in ordinary typing operation, means to set the computing mechanism in readiness for operation thereof and numeral keys in operative relation when the computing mechanism is thus set to simultaneously operate the typing and the computing mechanism, said typing mechanism being normally free from the load of said master wheel for normal operation of the typing numeral key levers without rotation of said master wheel in all positions of the typewriter platen.
138. A calculating mechanism comprising a casing attached to a typewriter, a totalizer and a master wheel therein movable step by step relative to each other, said movement being independent of typewriter carriage movement in ordinary typing operation, numeral actuators for said totalizer, the numeral key levers of the typewriter extending in the path traversed by said actuators, and means combined with said numeral actuators for coincidentally operating the numeral key levers of the typewriter, and means permitting use of the typewriter numeral keys at all times to type numerals without computing.
139. A calculating mechanism engaged with a typewriter having a frame and a carriage and comprising a totalizer having numeral wheels visible from in front of the typewriter, tabulating means for said mechanism and means for engaging said calculating mechanism with the typewriter frame, so as to permit simultaneous actuation thereof in all columnar positions of the carriage, said calculating mechanism permitting direct operation at all times of the numeral keys of the typewriter to write numerals without computing.
140. A calculating mechanism engaged with a typewriter including a key operated totalizer having numeral wheels visible from in front of the typewriter and operating mechanism including typing numeral levers normally inoperative upon the calculating mechanism, and calculating mechanism at all times in operative relation to said typing numeral levers, said operating mechanism permitting direct unimpeded use alternatively at will and at all times of the typewriter alone or of the combined machines to print through the typewriter, digits introduced into the totalizer.
141. A calculating mechanism comprising a casing, a totalizer operable therein, said casing adapted to be immovably attached in fixed position above the keys of a typewriter having a carriage, said totalizer being operable in all columnar positions of said carriage, said mechanism being arranged to utilize the printing mechanism of the typewriter for recording the number set up, the typewriter in normal operation thereof immediately upon complete entry of a number into the totalizer being operatively disconnected and free from the added load of the computing mechanism.
142. In a combined typewriter and adding machine, including a self-contained computing unit completely preassembled, disposed entirely above the numeral key levers of the typewriter, having a totalizer, a tabulator for said totalizer, a bank of number keys, said numeral key levers being disconnected from said computing unit immediately upon complete entry of a number into said unit, said machine being constructed and arranged to correctly set up in the totalizer and to print through the typewriter mechanism, any number within the range of the computing mechanism by performing a tabulating operation and then successively actuating those keys of the bank corresponding to the successive digits of the number.
143. A combined typewriter and calculating mechanism including a standard typewriter base carrying the entire mechanism including a typewriter carriage, said calculating mechanism including a totalizer, said typing mechanism including typewriter numeral key levers, means for actuating said totalizer and the numeral key levers simultaneously in all columnar positions of the typewriter carriage, said typing mechanism being free from the load of any part of said computing mechanism immediately upon completion of the entry of a number into the totalizer, said typing numeral keys being accessible at all times for typing operation.
144. A calculating attachment for a typewriter comprising a casing secured to the frame of a typewriter, a totalizer in said casing, means for moving said totalizer lengthwise so as to disclose numerals carried by its wheels through apertures in said casing, keys for operating said totalizer, and means combined with said keys for coincidentally operating the numeral key levers of the typewriter, said means avoiding interference with the normal use of the typewriter.
145. A calculating attachment for a typewriter comprising a casing secured to the frame of the typewriter, a totalizer in said casing, means for moving said totalizer lengthwise so as to disclose numerals carried by its wheels through apertures in said casing, selective means for operating said totalizer, and coincidentally causing the typewriter to print the numeral selected.
- Signed at New York city, in the county of New York and State of New York, this 14th day of December, 1920.
- MAURICE SAMBURG.
JULIUS C. HOCHMAN.
